UNITED STATES PATENT OFFICE.

WINTHROP K. HOWE, OF ROCHESTER, NEW YORK, ASSIGNEE TO GENERAL RAILWAY SIGNAL COMPANY, OF GATES, NEW YORK, A CORPORATION OF NEW YORK.

AUTOMATIC TRAIN-CONTROL SYSTEM.

Application filed April 1, 1916, Serial No. 28,364. Renewed May 2, 1921. Serial No. 466,216.

To all whom it may concern:

Be it known that I, WINTHROP K. HOWE, a citizen of the United States, and a resident of the city of Rochester, in the county of Monroe and State of New York, have invented a new and useful Automatic Train-
Control System, of which the following is a specification.

This invention relates to systems for automatically controlling the speed of railway trains so as to facilitate the movement of traffic on railroads without sacrificing safety.

In order that a system for automatically controlling the speed of railway trains may be applicable to the different conditions found in practice, it is desirable, for reasons quite generally understood and appreciated by those skilled in the art of railway signaling, that the system should provide for automatically governing the speed of a train to correspond to the speed which it should have if the conditions are such that the train should reduce its speed and proceed cautiously, whether this reduction in speed is required by the presence of another train, ahead, a sharp curve or dangerous grade, or the like. Also, the system should preferably be constructed so that it operates in accordance with principles and practices which are economical and safe; and in this connection it seems important to follow the principles and practices which have been found by long trial and experience in railway signaling to satisfy the exacting requirements of this kind of signaling. According to one of these principles which is generally used in railway signaling at the present time, and which has been adopted in this invention, although it is appreciated that certain features of the invention do not necessarily require the use of this principle, the track is divided into electrically isolated sections or blocks, each provided with a source of current and a relay or translating device; and the source

of current and the relay are so connected with the track rails of the corresponding section as to constitute a normally closed track circuit, this track circuit serving as a reliable means for detecting the presence of a train on a given portion of the track. In applying this principle of the normally closed track circuit to a system for automatically controlling railway traffic, it is necessary to recognize the fact, which is well known by

those skilled in the art of railroad signaling, that, in order to facilitate and expedite traffic, the blocks or track sections into which the track is divided in practice vary in length; and it is necessary that a system for automatically controlling railway traffic, before it can be applicable to present day conditions, must make proper allowances for this variation in the length of blocks or track sections.

A further condition found in practice for which it is desirable to make provision is that found at places where traffic is liable to become congested, as for instance at a station where passengers are taken on and let off, under these conditions it being desirable to permit trains to run closer together or to close up, providing they reduce their speed correspondingly.

Another condition which should be considered in designing a system for automatically controlling the speed of railway trains, is found principally at places, such as yards, crossings and the like, where the routes of different trains conflict, it being necessary in this case to make proper provision for bringing a train automatically to an absolute stop if it would interfere with the route of another train in continuing its movement.

With these considerations in view, this invention has for its objects to devise a simple and novel system for automatically controlling the speed of railway trains which will satisfy the conditions found in practice, such as those hereinbefore explained, and also to construct and arrange the parts of this system so that it will perform its necessary functions efficiently and reliably.

Other objects and advantages will appear as the description of the invention progresses; and the novel features of the invention are pointed out in the appended claims.

The invention primarily consists in the parts, in the arrangements and combinations of parts, and in the electrical connections and controlling circuits for said parts, all of which will be more fully set forth hereinafter.

The specific system disclosed herein is an improvement upon the system disclosed and claimed in my prior application Ser. No. 38,132, filed July 6, 1915.

In describing the invention in detail, ref-

erence will be made to the accompanying drawing in which is illustrated one preferred physical embodiment of the invention, in which like references to characters refer to like parts in the several views, and in which—

Fig. 1 is the diagrammatic illustration of an assumed lay-out of railroad track which has been selected to bring out the conditions with which this invention more particularly deals; Fig. 1 also showing the blocks or track sections, the control ramps or contact rails, selector ramps or tappets, the limits of control of each control ramp and the curves of permissive speed, all of which are more fully explained hereinafter.

Fig. 2 shows the parts of the system which are carried by the vehicle or train, together with their electrical connections and their control circuits, these parts being shown diagrammatically more with a view to making their functions and operations more easily understood than with regard to their exact construction and arrangement;

Figs. 3 and 4 are diagrammatic views of the parts of the track shown in Fig. 1, showing the control devices and their electrical connections of the parts of the system located along the track, the left hand end of Fig. 4 being a continuation of the right hand end of Figure 3;

Fig. 5 is the same as Fig. 2 with the emergency brake control omitted; and

Fig. 6 is the same as Fig. 3 with the control wires and contacts for applying low voltage to the ramps omitted so as to provide trackway equipment suitable for governing the modified form of car apparatus shown in Fig. 5.

Referring to the accompanying drawings, in Fig. 1 is illustrated two stretches of straight track T^1 and T^2 connected by reverse curves, also a third stretch of track T^3 which intersects the stretch of track T^2 near its righthand end. It is assumed that near the middle of the stretch of track T^2 is located a station, and that the switch connecting the stretch of track T^2 with the stretch of track T^3 and the signals M and N governing the movements of trains over these stretches of track are controlled in the usual manner by an interlocking machine located in the tower W. It should be understood that Fig. 1 illustrates merely an assumed lay-out which is selected because it appears to bring out clearly the different features and characteristics of the invention, and that the invention is in no wise restricted to the particular arrangement of the stretches of track, curves, location of station, etc. but is applicable to various other arrangements and combinations.

One of the track rails 2 of the stretches of track T^1 and T^2 and the connecting curves is divided by insulating joints 3 into track

sections or blocks, designated A to J inclusive. These blocks may be of any length necessary to obtain the desired spacing of trains, but in practice these blocks preferably would not be exactly of the same length, for reasons well known to those skilled in the art of railway signaling and more fully explained hereinafter. For the purpose of rendering more intelligible the features of construction and operation of the system embodying this invention, without unduly complicating the illustration and description, it is assumed that the combined length of the blocks B and C, of the blocks F and G, of the blocks G and H and of the blocks H and I is substantially equal to the length of the block A; whereas each of the blocks D and E are shorter than the block A. It is to be understood, however, that the particular successive occurrence of the different length blocks illustrated is not compulsory and that the invention is in no way restricted to the particular arrangement and lengths of blocks illustrated, since several blocks of the same length may follow each other and then any number of longer blocks or shorter blocks arranged end to end or overlapping, and so on in any sequence or combination. The normal direction of traffic over the stretches of track T^1 and T^2 is indicated by an arrow marked "Traffic".

Associated with each track section or block, A to J inclusive, is a ramp or contact rail R, the ramps for the different blocks being designated RA, RB, and so on, and being preferably located at the entrance to the corresponding block. These ramps are of any suitable construction or of any desired length, and may be located on either side of the track, or between the track rails 1 and 2; but these ramps are insulated from the track rails 1 and 2 and are so arranged that a contact shoe or similar device carried by the train may make electrical contact with these ramps and also be operated mechanically by engagement with said ramps.

Limits of control of the ramps.

The limits of control of each of the ramps RA, RB and so on, are indicated in Fig. 1 by horizontal lines extending between certain vertical lines extending downwardly from the insulating joints 3 at the entrance to each block and designated a, b, and so on, each of these horizontal lines indicating the limits of control being connected at one end by a dot to one of the vertical lines a, b, and so on, and terminating at its other end in an arrow. For example, the limit of the control of the ramp RB is from the insulating joint 3 at the entrance of the block B to the insulating joint 3 at the entrance of the block D; and this limit of control indicates that whenever either of the blocks B or C is occupied by a train, the ramp RB should

be in the condition to have an effect on the speed control apparatus of the train corresponding to a stop signal, and that the ramp RA should be in a condition corresponding to a caution signal.

Curves of permissive speed.

Below the horizontal lines hereinbefore described, which indicate the limits of control of different ramps R, are a series of curves which indicate permissive speeds at different points along the stretch of track T¹ and T². These curves are drawn in accordance with the well known method of plotting speed and distance curves to rectangular coordinates, and are derived from the braking curves of the kind of train equipment traveling over the railroad. In case there are different kinds of train equipment having different braking curves, it is desirable for safety to arrange the block lengths and the curves indicating permissive speeds, so as to properly protect the heaviest and fastest train which may run on the railroad.

A brief explanation of the curve of permissive speed may serve to make it easier to understand the relation which these curves bear to the entire system. In these curves the horizontal distances represent the distance of travel of the train over the successive blocks to any arbitrary scale, which in general, with the particular exception of the blocks D and E corresponds in scale with that to which the blocks A to J are drawn; and vertical distances represent permissive speeds to an arbitrary scale of speed in miles per hour, or in any other suitable units. The lower horizontal line 4 represents zero speed, and the horizontal line 5 represents some predetermined low speed such as five miles per hour, or ten miles per hour, or some other arbitrary figure which seems best adapted to the particular conditions of the railroad in question. The curves of permissive speed for the different blocks or combinations of blocks are based on the same principles, and the description of one will suffice for all. Referring to the block A, the curve 6 (the curve drawn as a full line) represents, for each point in the length of the block A, the permissive speed at that point. Generally speaking, this curve 6 is equivalent to the braking curve for the fastest and heaviest train which the system is designed to protect, due allowances being made for the physical characteristics of the block A, such as its grade, curves or other factors affecting the braking distance of the train. It will be noted that this curve 6 intersects the line 5 indicating the predetermined low speed, in this case assumed to be ten miles per hour, at a short distance from the end of the block A. The curve 6 is drawn in this way because it is assumed that the speed control system

embodying this invention does not automatically bring the train to a complete stop at the end of each block but only to the predetermined low speed. The distance between the point, where the curve 6 intersects the line 5 of the predetermined low speed, to the vertical line b at the end of block A, may be of any length desired, and is adopted principally as a factor of safety.

The significance of the curve 6 may be better understood by some illustrations; and for instance, assume that the train enters block A, at a speed of approximately fifty-five miles per hour, and that another train occupies block B. Under these conditions it can be seen from the curve 6 that the first mentioned train entering block A should have the brakes immediately applied in order that this train may be brought to a predetermined low speed by the time it reaches the end of the block A. Suppose, however, that a train enters the block A at the speed of about thirty miles per hour, and that the block B is occupied by another train; then, under these conditions the first mentioned train entering the block A need not commence to reduce its speed immediately, but may proceed some distance into the block A before its brakes have to be applied, this distance being readily determined by continuing the horizontal line corresponding to the speed of this train and finding out where this horizontal line intersects the curve 6, due allowance being made for time required for the application of the brakes and for the brakes to attain their full braking effect.

For the next illustration, assume that when a train enters the block A, neither of the blocks B nor C is occupied by another train; then under these conditions the first train entering the block A is not required to reduce its speed while traveling through the block A, and may attain any speed consistent with safety. The safe speed which the train may attain in the block A depends upon the special local conditions, which may permit comparatively high speed or may require comparatively low speed. Furthermore, the speed which it is safe for the train in the block A to travel must not be so great that, when it enters the block B, it will be traveling too fast to be brought by its brakes to the predetermined low speed by the time it reaches the end of the block C, since it may well happen that while neither of the blocks B nor C is occupied by a train, another train may occupy the block D and be located just ahead of the insulating joint 3 at the entrance of the block D. For these reasons it is contemplated according to this invention to make provision for limiting the maximum speed which a train may attain in the block A, even though the traffic conditions permit the train to proceed at full

speed through the block A. This limitation upon the permissive maximum speed of a train under a proceed signal is obtained by reason of the construction and arrangement of certain parts of the system carried on the train, as explained more fully hereinafter, and these parts operate providing a train in the block A attains a speed greater than that indicated by the 5 horizontal dash line 7, it being possible, however, for a train to travel through the block at any lower speed. The curves of permissive speed shown in Fig. 1 and described briefly hereinbefore, may be derived 10 from the braking curve of the heaviest and fastest train traveling on the railroad, either for an emergency application of the brakes, or for a so-called service application of the brakes, or for any other suitable 15 application of the brakes, as may be desired; and it should be understood that these curves of permissive speed illustrated in Fig. 1 are not intended to be quantitatively precise but merely represent certain 20 assumed conditions.

Construction of parts located along the track.

Referring to Figs. 3 and 4, at each end of 30 each block A to J inclusive, preferably at the exit end, a track battery 8 is connected across the track rails 1 and 2; and at the other end of each block a track relay 9 is connected across the track rails 1 and 35 2. The track battery 8 and track relay 9, together with the track rails 1 and 2 of the corresponding block, constitute the well known normally closed track circuit, the operation of which will be clear to those skilled in 40 the art of railway signaling without further explanation. The track relays 9 are provided with armatures or contact fingers illustrated according to established convention, some of said relays having two armatures and others four armatures; and for 45 simplicity the track relays of the blocks B, C and so on, and their corresponding armatures, are given the same reference characters as the track relays and its armatures 50 of the block A, with the distinctive exponents "1," "2" and so on added thereto. The armatures of the track relays 9 control circuits for connecting sources of current of different intensities, in this instance 55 shown as batteries 14, 15 and 16, across the ramp at the entrance to the corresponding block and one of the track rails, as the track rail 1; but the different electrical connections between the ramps and the armatures and cooperating contacts of the track relays 9 will not be set forth in detail, since the different controlling circuits 60 will be more fully explained hereinafter.

65 Located along the trackway, preferably between the track rails 1 and 2, are suit-

able selector ramps, designated SR, SC and SL, and these selector ramps are located at different distances from one of the track rails in order to determine the particular selection obtainable by a particular group 70 of selector ramps. These selector ramps act like cams or similar devices to actuate mechanically cooperating shoes or tappets carried by the train; and to perform this function, said selector ramps may be supported in any suitable way, preferably resiliently, and are so shaped with sloping ends as to engage the selector shoes carried by the train with the least amount of shock and wear. Also, these selector ramps may be of any length desired or found necessary 75 to operate the selector shoes carried by the train at the different speeds of the train without undue shock. The particular location of the selector ramps in the length of 80 the stretches of track, and the effect produced by them upon the apparatus carried on the train will be more fully explained herein- 85 after.

Construction of parts carried on the train.

Referring to Fig. 2, the train or vehicle is illustrated diagrammatically as comprising two pairs of wheels and their connecting axles, designated 17—18, 20—21, and 19 and 22 respectively, it being understood that the axles 19 and 22 will in practice be connected by some suitable frame. The devices on the train for establishing the permissive speeds 90 at different points in its travel, and also for establishing its actual speed, are connected by suitable gearing to one of the axles of the train, preferably to an axle attached to wheels which are neither driven nor braked. In the particular construction illustrated, a worm 23 is secured to the front axle 22 in mesh with a worm gear 24 secured to the lower end of a shaft 25, said shaft 25 being mounted in suitable bearings (not shown). Secured to the upper end of the shaft 25 is 95 a beveled gear 26 which meshes with a mating beveled gear 27 fixed to a shaft 28, said shaft 28 being journaled in suitable supports or bearings 29 and 30. Fixed to the shaft 100 28 is a bifurcated member 31, and pivoted to the outer end of each of the bifurcations of said member 31 is a weighted arm 32 having integral therewith a toothed sector 33. Mounted on the shaft 28 to turn therewith and so as to be capable of longitudinal movement thereon, and also relative to the bearing support 30, is a sleeve 34 which has 105 on opposite faces thereof teeth adapted to mesh with the teeth of the sectors 33. This sleeve 34 has secured thereto at its lefthand end two spaced collars 35, and interposed between the outer collar 35 and an enlarged head 36 on the shaft 28 is a compression coil 110 spring 37. Below the shaft 28 and the sleeve 34 carried thereon is a shaft 38, which is 115

disposed in a plane substantially at right angles to the plane of said shaft 28, said shaft 38 being journaled in suitable supports 39 and 40. Fixed to one end of the shaft 38 is an arm 41 extending upwardly; and the upper end of this arm 41 is bifurcated and straddles the sleeve 34 between the collars 35, suitable pins or rollers 42 being secured in the bifurcations of said 5 arm and extending into the space between the collars 35. Secured to the shaft 38 are two downwardly projecting curved arms 43 and 44 having contact studs 45 secured to their lower ends, but insulated from the 10 body portions of said arms. Loosely mounted on the shaft 38 adjacent to each of the arms 43 and 44 is an arm or lever, designated 46 and 47, the upper end of which is provided with a freely revolvable roller 48, 15 and the lower end 49 of which extends downwardly into position to make contact with the contact stud 45 of the corresponding arm 43 or 44, as the case may be; and the downwardly projecting extension 49 of 20 each arm 46 and 47 is connected to the corresponding arm 43 or 44, as the case may be, by a tension spring 50.

Arranged substantially parallel with the shaft 38 is a shaft 51 journaled in suitable 25 bearings or supports 52 and 53; and secured to this shaft 51 are two cams 54 and 55, each disposed in the plane of one of the arms 46 or 47. These cams 54 and 55 are so arranged that when the shaft 38 and the 30 arms 46 and 47 carried thereby, are rocked in a clockwise or counter-clockwise direction, the rollers 48 carried by said arms engage said cams at a point, indicated at α . These cams 54 and 55 are shown as symmetrical about a line extending from the 35 point α through the center of the shaft 51, so that a rotation of the shaft 51 and the cams 54 and 55, either clockwise or counter-clockwise from their normal or neutral position, shown in Fig. 2, will produce substantially the same movement of the cooperating rollers 48. In other words, since the cams 54 and 55 are symmetrical, the same effect is produced when the vehicle is traveling in either direction. The function of the 40 cams 54 and the relation which they bear to the curves of permissive speed, hereinbefore referred to, will be pointed out more fully hereinafter in a description of the operation.

One end of the shaft 51 extends to a point approximately in the plane of the shaft 28, and secured to this end is a gear wheel 56. The shaft 51 is biased by suitable 45 means to assume an initial position, corresponding to that shown in Fig. 2; and in the simplified construction illustrated, this bias is produced by a counterweight 56¹ suitably attached to the gear 56 so as to be directly under the shaft 51 when said shaft is in the 50 desired initial position. The gear 56 is also provided with a small cut-away portion 56² for the purpose hereinafter explained. Above the gear wheel 56 is a shaft 57, having secured thereto a worm wheel 58 adapted to mesh with the teeth of said gear 56; and this shaft 57 is connected to the head 36 of the shaft 28 by a universal coupling 59 of suitable construction, so that the shaft 57 may move up and down to bring the worm gear 58 out of and into engagement 55 with the gear wheel 56 without interfering with the rotation of the shaft 57. On the outer end of the shaft 57 is loosely mounted a collar or bearing 60; and arranged above this collar is a solenoid 61, having a core 62. 60 The lower end of the core 62 is bifurcated and straddles the collar 60, each of the bifurcations of said core being pivotally connected to said collar 60 by a pin 63.

A contact shoe is carried by the train in 65 any suitable way in position to cooperate with the ramps R, and in the particular construction shown, this contact shoe is illustrated diagrammatically as mounted upon a bracket 64, which for simplicity is assumed to be of insulating material and which is suitably mounted upon one of the journal boxes of the axle 19. Mounted on the bracket 64 is a vertically movable plunger 65, which has a collar 66 secured thereto near its lower end and is pressed downwardly by a compression coil spring 67 interposed between said collar 66 and the 70 under face of the bracket 64. To the upper end of the plunger 65 is fixed a button 68 of insulating material, which, being larger than the plunger 65, engages the upper face of the bracket 64 and limits the downward movement of said plunger 65. The 75 plunger or shoe 65 is arranged in substantially the same plane as the ramps R and is designed to make electrical contact with said ramps as the train passes them, and also to actuate a suitable circuit controlling device. To enable the shoe or plunger 65 to 80 perform this circuit controlling function, a contact spring 69 is secured to the bracket 64 to extend over the insulating button 68 of the shoe 65 and is 85 disposed in position to make contact with a contact member 70, also secured to the bracket 64, when the shoe 65 is in its lower position. When, however, the shoe 65 is 90 raised by engagement with a ramp R, the insulating button 68 strikes the contact spring 69 and raises it out of contact with the contact member 70.

The selector mechanism which cooperates 95 with the selector ramps to perform certain selecting functions at certain points in the travel of the train may be of any suitable construction, but is shown diagrammatically as comprising a plate or panel 71, assumed to be of insulating material, which is fastened 100 in any suitable way to the axle 19. Se- 105

125

130

cured to the panel 71 are two lugs or ears 72 which support a rod or shaft 73; and mounted loosely on this rod 73 are three selector tappets, designated 74, 75 and 76, 5 these selector tappets being capable of rocking up and down on the rod 73 independently of each other, and being provided with suitable means (not shown) which prevents movement of said tappets lengthwise of the rod 73. The downward position of said tappets is determined by suitable means shown in the simplified construction as a cross bar 72¹ fastened to the lug 72 and extending under the tappets. The actuation 10 of the selector tappets 74, 75 and 76 by the corresponding selector ramps SR, SC or SL, may bring about the selection in any way, either mechanically or electrically, but in 15 the particular construction illustrated the selector tappets are provided with upwardly extended contact arms, designated 77, 78 and 79, which are arranged to move into and out of contact with suitable contacts, indicated 20 diagrammatically by arrows. The opening and closing of certain electric circuits by the actuation of the selector tappets 74, 75 and 76 causes an energization or deenergization 25 of certain electromagnets or relays, herein-after termed selector relays, two of which 30 are shown in Fig. 2 and designated 80 and 81. These selector relays 80 and 81 are provided with suitable circuit controllers, which 35 are represented in the drawing according to established convention and which are designated 82, 83 and 84, 85 respectively.

The apparatus of the system carried on the train is controlled by two car relays K and S, having armatures 86, 87, 88 and armatures 89, 90, respectively, the control relay K serving to control the operation of the part of the apparatus which controls the speed of the train, and the stop relay S controlling the parts of the apparatus which operate to bring the train to an absolute stop.

45 The speed control system embodying the invention may be used with or without fixed signals located along the track; but in the embodiment of the invention illustrated cab signals are given aboard the train by colored lights, the green lamp G being lighted to indicate proceed, and the yellow lamp Y being lighted to indicate caution.

55 For this automatic train control system it is assumed that the train or vehicle is equipped with the ordinary type of pneumatic brakes, which includes the usual train pipe 91. Since the construction
60 and operation of the pneumatic system of brakes is well known, it is deemed unnecessary to show and describe the construction and operation of this system in detail, it being sufficient for a clear understanding of this system to know that the brakes are automatically ap-

plied on the train when the train pipe 91 is vented, and that the distinction as to whether or not an emergency application or a service application of the brakes occurs ordinarily depends upon the rapidity with 70 which the train pipe 91 is vented. The venting of the train pipe 91 at different rates to obtain either an emergency application or a service application of the brakes may be obtained in different ways, but in 75 the diagrammatic illustration shown, the train pipe 91 connects to two electrically operated valve mechanisms, designated EB and SB. It is deemed unnecessary to enter into a detailed illustration and description 80 of the construction and operation of these electrically operated valves EB and SB since various devices, capable of accomplishing their necessary functions, are well known in the art, it being sufficient for the 85 present purposes to understand that the deenergization of the electrically operated valve SB causes a venting of the train pipe 91 sufficient to cause a service application of the brakes, and in the same way a de- 90 energization of the electrically operated valve EB causes an emergency application of the brakes.

In Fig. 2 a ramp R is shown in position 05 to cooperate with the plunger or shoe 65 when the train advances; but, instead of controlling, by means of track relays, the difference of potential established between this ramp R and a track rail 2 by the batteries 93, 94 and 95, a switch 96 is arranged, for simplicity, to engage certain contact studs 97, 98 and 99, which are so arranged that when the switch 96 is in contact with the contact stud 97 the combined potential difference of the batteries 93, 94 and 95 is 105 established between the track rail 2 and the ramp R by a circuit as follows: starting at the track rail 2, conductor 100, batteries 93, 94 and 95 in series, conductor 101, contact stud 97, switch 96 and conductor 110 102 to the ramp R. When the switch 96 is moved into contact with the contact stud 98 the combined difference of potential of only two of the batteries 93 and 94 is established across the track rail 2 and the ramp 115 R by a circuit which can be easily traced by analogy to the circuit just above traced, and in the same way when the switch 96 is in contact with the contact stud 99 a difference of potential equal to only one of the batteries 93 is established between the track rail and the ramp R. These potential differences of different intensities will be hereinafter referred to as high, medium and low differences of potential. 120 125

Operation in general.

Before setting forth in detail the operation of the different parts of the system embodying this invention and before tracing 130

the different circuits, it seems instructive to consider briefly a general outline of the operation of the system together with the principal functions performed by the parts of the system. As a train approaches each block, or a number of blocks having substantially the same physical characteristics, as length, grade, curves and the like, the train passes over a number of selector ramps

10 SC, SR or SL, which are arranged in a predetermined way between track rails so as to effect certain successive movements of the selector tappets 74, 75 or 76 to energize and maintain energized one of the selector 15 relays 80 or 81, so that the speed of the train in the block or blocks next entered will be controlled by the cam corresponding to the selector relay energized. Then, as the train is about to enter each block and the first 20 contact shoe on the train strikes the ramp R at the entrance to that block, automatic control of the speed of the train is provided for by certain circuits and movements of parts, in general as follows:

25 First, the parts of the system controlling the speed of the train, in case the train has been running under dominance of this speed control apparatus, are restored to their normal or idle position, so that it relieves the 30 train from the limitations upon its speed to which it has been previously subjected. This operation is, however, dependent upon traffic conditions in the block into which the train is about to enter, and if danger 35 conditions exist in this block, the parts are not reset or restored to their normal position, but remain in the position they have at the time, the result being that the train, if it enters this next block, must do so at a 40 speed lower than the predetermined low speed hereinbefore mentioned.

Second, when the first pair of wheels and axle enter a block, as the block B, assuming that neither the blocks B nor C is occupied, 45 and that the parts of the speed control apparatus have already been restored to their normal position, this speed control apparatus is made subject to the traffic conditions of the next block in advance, as the 50 block D, so that, if this block D is occupied, the green lamp G giving the proceed signal is extinguished, the yellow lamp Y giving the caution signal is lighted, and then later, when the combined conditions of the actual 55 speed of the train and its distance from the point of danger are such that the brakes should be applied, the cooperation of the cam 54 or the cam 55 and the speed indicating device or governor causes the automatic 60 application of the brakes. However, if no danger conditions exist in this next block in advance, as the block D, the parts of the speed control apparatus are retained in their normal or idle position and permit the train 65 to proceed without any restriction upon the

speed which it may attain, except that it may not exceed the predetermined maximum speed limitation for the block it is in.

There are other features of the operation of the system embodying this invention 70 which are not included in the above general description of the operation, but these particular features will be made clear thereafter.

In describing the operation, occasion will 75 be had to refer to different controlling circuits from time to time and for simplicity and also to avoid unnecessary repetition, these controlling circuits as they are described and traced will be given designating 80 numbers and will thereafter be referred to by these numbers. Because of the number of circuits involved, a reference table, giving the number of each circuit and a 85 brief statement of the function performed by that circuit, is given as follows:

Circuit number	Function	Page
One	Normally energizes the control relay K.	90
Two	Gives the proceed signal by lighting the green lamp G.	
Three	Normally energizes the cam starter magnet 61.	
Four	Normally energizes the stop relay S.	
Five	Normally energizes the valve EB controlling the emergency brakes.	
Six	Preliminarily energizes the selector relay 81.	95
Seven	Maintains the selector relay 81 energized.	
Eight	Energizes valve SB controlling the service brakes when the selector relay 81 is effective.	
Nine	Preliminarily energizes selector relay 80.	
Ten	Maintains selector relay 80 energized.	
Eleven	Energizes valve SB controlling the service brakes when the selector relay 80 is energized.	
Twelve	Maintains the control relay K energized when the shoe is on an energized ramp.	100
Thirteen	Maintains the stop relay S energized when the shoe is on an energized ramp.	
Fourteen	Gives the caution signal by lighting the yellow lamp Y.	

Operation of the parts of the system on the train.

The parts of the system embodying this invention which are carried on the train are shown in Fig. 2 in the normal or idle position in which the train may proceed to any speed lower than the predetermined maximum speed for the block it is occupying at the time. The operation of replacing or restoring these parts to their normal or idle position after they have been operated will be taken up later in the description of the operation. When the parts of the system are in their normal or idle position the control relay K is normally energized by current supplied from a local source of current carried by the train, as the battery 92, along a circuit which may be traced as follows:

Circuit Number One.

From the battery 92, conductors 105, 106, 107, 108, 109, 110 and 111, armature 86 of the control relay K in its upper position, conductors 112 and 113, control relay K, conductors 114, 115 and 116, contact member 70,

125

119

113

120

130

contact spring 69, and conductors 117, 118, 119 and 120 back to battery 92.

When the control relay K is energized and its armature 88 is in its upper position, the green lamp G is lighted by a circuit which may be traced as follows:

Circuit Number Two.

From the battery 92, conductors 105, 106, 107, 108, 109 and 121, armature 88 of the control relay K in its upper position, conductor 122, green lamp G, and conductors 123, 124, 125 and 120, back to the battery 92.

Also, when the control relay K is energized and its armature 87 is in its upper position, the cam starter magnet 61 is supplied with current from the battery 92 flowing in a circuit which may be traced as follows:

Circuit Number Three.

From the battery 92, conductors 105, 106, 107, 108, 109, 110 and 126, armature 87 of the control relay K in its upper position, conductors 127, cam starter magnet 61, and conductors 128, 124, 125 and 120, back to the battery 92.

When the parts of the system are in their normal position, the stop relay S is normally supplied with current from the battery 92 flowing in a circuit which may be traced as follows:

Circuit Number Four.

From the battery 92, conductors 105, 106, 107, 108 and 129, armature 89 of the stop relay S in its upper position, conductors 130 and 131, stop relay S, conductors 132, 115 and 116, contact members 70, contact spring 69, and conductors 117, 118, 119 and 120, back to the battery 92.

When the stop relay S is energized and its armature 90 is in its upper position, the electrically operated valve EB, controlling the emergency application of the brakes, is energized by a circuit which may be traced as follows:

Circuit Number Five.

From the battery 92, conductors 105, 106, 107 and 133, armature 90 of the stop relay S in its upper position, conductor 134, electrically operated valve EB and conductors 135, 119 and 120, back to the battery 92.

It is assumed that the parts of the system on the train are shown in Fig. 2 in the positions which they assume after the train has passed suitable selector ramps SC and SR which have prepared the speed control apparatus for controlling the speed of the train as it enters the block A, or a block having the same physical characteristics. When the train passes these selector ramps, the selector tappet or shoe 76 is raised to the position where its contact arm 77 closes the circuit for energizing the selector re-

lay 81, which circuit may be traced as follows:

Circuit Number Six.

From the battery 92, conductors 105 and 136 to the rod 73 on which the selector shoe 76 is mounted and with which it makes electrical contact, thence along the contact arm 77 of said selector shoe 76, conductors 137 and 138, selector relay 81, conductors 139, 140, 141, 142, 118, 119 and 120, back to the battery 92.

The last traced circuit (Number 6) energizes the selector relay 81 and actuates its armatures 84 and 85 to their upper position, as shown in Fig. 2. With the armature 84 of the selector relay 81 in its upper position, and with the middle selector shoe 75 in its lower or normal position, a circuit for maintaining the selector relay 81 energized is established as follows:

Circuit Number Seven.

From the battery 92, conductors 105 and 136, rod 73, middle selector shoe 75, contact arm 78, conductors 143 and 144, armature 84 of the selector relay 81 in its upper position, conductors 145 and 138, selector relay 81, and conductors 139, 140, 141, 142, 118, 119 and 120, back to the battery 92.

When the selector relay 81 is energized, the speed of the train is determined by the cam 55, and electrically operated valve SB, which controls the service application of the brakes, is normally energized to prevent occurrence of the service application of the brakes by a circuit controlled by the cooperation of the cam 55 and the speed arm 46, said circuit being as follows:

Circuit Number Eight.

From the battery 92, conductors 105, 106, 146, electrically operated valve SB, conductors 147 and 148 extension 49 of the lever 46, contact stud 45 carried by the arm 43, conductor 149, armature 85 of the selector relay 81 in its upper position, and conductors 150, 142, 118, 119 and 120, back to the battery 92.

In case right hand selector shoe 74 had been raised instead of the left hand selector shoe 76, as would be the case when the train passes a selector ramp SL, the selector relay 80 would have been energized to make the speed of the train subject to the control of the cam 54, the circuit for energizing the selector relay 80 when the selector shoe 74 is raised being as follows:

Circuit Number Nine.

From the battery 92, conductors 105, 136, rod 73, selector shoe 74, and its contacting arm 79, conductors 151 and 152, selector relay 80 and conductors 153, 140, 141, 142, 118, 119 and 120, back to battery 92.

The selector relay 80 is maintained ener-

gized, after it has once been energized, so long as the middle selector shoe is in its lower position, by a circuit analogous to circuit Number Seven, hereinbefore traced, 5 said maintaining circuit of the selector relay 80 being as follows:

Circuit Number Ten.

From the battery 92, conductors 105 and 10 136, rod 73, middle selector shoe 75 and its contacting arm 78, conductors 143 and 154 armature 82 of the selector relay 80 in its upper position, conductors 155 and 152, selector relay 80 and conductors 153, 140, 141, 15 142, 118, 119 and 120, back to battery 92.

When the selector relay 80 is energized and the speed of the train is controlled by the cam 54, the circuit for energizing the valve SB is as follows:

20 *Circuit Number Eleven.*

From the battery 92, conductors 105 and 146, valve SB, conductors 147 and 156, extension 49 of the lever 47, contact stud 45 25 of the arm 44, conductor 157, armature 83 of the selector relay 80 in its upper position and conductors 158, 141, 142, 118, 119 and 120, back to the battery 92.

Assume that the parts of the system 30 carried by the train are in their normal position, as shown in Fig. 2, and that the contact shoe 65 engages a ramp R between which and a track rail, as 2, a high difference of potential exists, such as is the case 35 when the switch 96 is in the position shown in Fig. 2. When the contact shoe 65 engages the ramp R two effects are produced: first, the shoe is lifted mechanically and breaks the electrical connection between 40 the contact member and the contact spring 69; and, second, the contact shoe 65 makes electrical contact with the ramp R. The mechanical movement of the contact shoe 65, and the resulting separation of the contact spring 69 from the contact member 70, interrupts the circuit Number One and the circuit Number Four which normally energize the control relay K and the stop relay S, respectively, so that unless the current is supplied to these relays from some other source than the battery 92, these relays will become deenergized and their armatures will drop. Also, since the circuits 50 Nos. One and Four include the armatures 86 and 89 of the control relay K and the stop relay S, respectively, these circuits will not be re-established, after said relays have once dropped, when the contact shoe 65 leaves engagement with the ramp R and is returned by the spring 67 to its lower or normal position. In this way, the mechanical cooperation of the contact shoe 65 with each ramp R as the train passes that ramp renders ineffective the circuits which normally maintain the control relay K and the

stop relay S in their normal or idle condition, so that said relays will operate to place the train under the control of the respective devices governed thereby at each ramp unless something else happens to retain said relays in their normal or idle condition.

When the contact shoe 65 makes electrical contact with the ramp R the partial circuit along the track terminating at the track rail 2 and at the corresponding ramp R is connected to the terminals of partial circuits simultaneously governing the control relay K and the stop relay S, whereby the potential difference which exists between the track rail and the ramp R may cause a flow of current through said relays to maintain them in their normal or idle condition. The complete circuit for the control relay K is as follows:

85 *Circuit Number Twelve.*

Commencing at the ramp R, through the contact shoe 65, conductors 159, 115 and 114, control relay K, conductors 113, 160 and 161 to the wheels and axles of the train, thence to the track rail 2, along conductor 100 through the batteries 93, 94 and 95 in series, conductor 101, through the switch 96 closed on contact stud 97, and along conductor 102 back to the ramp R.

The circuit for energizing the stop relay S by current derived from the batteries along the track is analogous to the circuit above traced for the control relay K and is as follows:

100 *Circuit Number Thirteen.*

Commencing at the ramp R, shoe 65, conductors 159, 115 and 132, stop relay S, conductors 131, 162 and 161, wheels and axles of the train, track rail 2, conductor 100, batteries 93, 94 and 95 in series, conductor 101, switch 96 closed on contact stud 97, and conductor 102 back to the ramp R.

When a high difference of potential exists between the ramp R and a track rail 2 the current flowing in the circuits Numbers Twelve and Thirteen is strong enough to energize the control relay K and the stop relay S sufficiently to raise their respective armatures to their upper position, if these armatures happen to be in their lower position, said current being also strong enough to maintain the armatures of said relays in their upper position if they are already there. In case a medium difference of potential, equivalent to that of two of the batteries 93 and 94 in series, exists between the track rail 2 and the ramp R, as would be the case when the switch 96 is closed on the contact stud 98, current will be supplied to the control relay K and the stop relay S along circuits substantially the same as circuits Numbers Twelve and Thirteen,

- and which can be easily traced by analogy to said circuits. This medium difference of potential supplies sufficient current to the control relay K to maintain its armatures in their upper position providing they are already in their upper position; but this current is not strong enough to raise the armatures of said relays from their lower position. This characteristic of the control relay K, whereby it is responsive to currents of different intensities, may be obtained in different ways, well known in the art, and it is deemed unnecessary to show and describe in detail the construction, the proportioning of the windings and counterweights, and other features which enable it to perform this selective function. In case a low difference of potential, equivalent to the battery 93 alone, exists between the track rail 2 and the ramp R, the current flowing through the control relay K is insufficient to maintain the armatures of said relay in their upper position; and, consequently, when the contact shoe 65 engages a ramp between which and a track rail only a low difference of potential exists, the armatures of the control relay K are dropped. In this connection it is noted that the stop relay S is designed so that the small current derived from the low difference of potential flowing through its coils will maintain its armatures in their upper position, the armatures of said stop relay being dropped only in case there is no difference of potential between the ramp R and a track rail.
- From the foregoing it can be seen that when a train passes a ramp connected to the three batteries 93, 94 and 95 in series, that the armatures of both the control relay K and the stop relay S will be restored to their upper position, in case they are in their lower position, or will be held in their upper position if they are in their upper position at the time. Also, when the train passes a ramp connected to two of the batteries 93 and 94 in series the armatures of the control relay K will be held in their upper position, providing they are already there, but will not be raised from their lower position; and if the ramp is connected to only one of the batteries, as 93, the armatures of the control relay K will drop, while the armatures of the stop relay S will still be held in their upper position. When the train passes a ramp entirely disconnected from any source of current, the armatures of the stop relay S will drop, and likewise the armatures of the control relay K, although, under normal operating conditions, the armatures of the control relay K would be in their lower position at the time the train passes a totally deenergized ramp.

Referring again to the case where the armatures of the control relay are dropped by the engagement of the contact shoe 65 with

a ramp between which and the track rail only a low difference of potential exists, the dropping of the armature 88 interrupts the circuit Number Two for lighting the green lamp G and closes a circuit for lighting the yellow lamp Y as follows:

Circuit Number Fourteen.

From the battery 92, conductors 105, 106, 107, 108, 109 and 121, armature 88 of the control relay K in its lower position, conductor 163, yellow lamp Y and conductors 164, 125 and 120 back to the battery 92.

In this way the engineer or motorman is advised that he should proceed cautiously and take measures to bring his train to a stop or to a predetermined low speed by the time he reaches the end of the block he has just entered.

The dropping of the armature 87 of the control relay K interrupts the circuit Number Three which normally energizes the cam starter magnet 61, thereby permitting the shaft 57 to drop by its own weight and bring the worm gear 58 into mesh with the gear 56. Since the shaft 57 is connected by the universal coupling 59, through the shaft 28, beveled gears 27 and 26, shaft 25 and gears 24 and 23 to the axle 22 of the train, the cam shaft 51 is turned as the train travels along the track exactly in proportion to the distance traveled by the train. The parts are preferably so proportioned that the cam shaft 51 will be turned nearly 180° when the train travels the length of the longest block occurring on the railroad in question. The shape of the cams 54 and 55, as stated hereinbefore, is determined from the curves of permissive speed for the particular train upon which they are mounted, the curves of permissive speed being in turn derived from the braking curve of the train in question. It can be seen from a study of Fig. 1 and a consideration of the explanation hereinbefore given of the curves of permissive speed, that it is possible to determine from these curves a permissive speed for the train at each point in its travel through a block; and the cams 54 and 55 are intended to reproduce the curves of permissive speed for two different blocks of different length and different physical characteristics. In the particular kind of cam shown, the lengths of the radii of the cam represent different permissive speeds, and the angular displacement of said cam from its initial or normal position (shown in Fig. 2) represents different distances traveled by the train, it being understood that the exact dimensions of the cam are proportional to the quantities which they represent. In short, the cams 54 and 55 represent for different blocks a predetermined functional relation between the speed of a train and the distance traveled by that train. The effective action of the

- cams 54 and 55 takes place along the line of movement of their respective followers, namely, the rollers 48 of the arms 46 or 47, and this line of movement may be assumed for practical purposes to be an arc of a circle indicated in Fig. 2 by the dash line 165. The radius of each cam 55 or 54, to the point where the line of action 165 intersects the periphery of the cam, represents the permissive speed for the train at the particular point in its travel corresponding to the angle through which the cam has been displaced from its initial position at that instant. It should be understood that the cams 54 and 55 are shown for illustrative purposes only and that the shapes of the cams shown are not intended to be quantitatively precise.
- The actual speed of the train is represented by the displacement of the shaft 38 from its initial or normal position (shown in Fig. 2), since the shaft 28 is turned at a rate proportionate to the speed of the train, and as the speed of the train varies the weighted arms 32 are thrown outward by centrifugal force against the opposition of the spring 37 more or less so that the position assumed by the collars 35 and the upper end of the arm 41, corresponds to the actual speed of the train at each instant. In Fig. 2 the parts are shown in the position corresponding to zero speed, the spring 37 having forced the sleeve 34 to the right until one of the collars 35 engages the support 30; and as the speed of the train increases the shaft 38 is turned in a counterclockwise direction, carrying with it the arm 43, which in turn by reason of the spring 50, rocks the lever 46 and moves the roller 48 toward the cam 55. The parts are so proportioned that when the actual speed of the train, represented by the displacement of the arm 46, is nearly as great as the permissive speed of the train at that instant, the roller 48 will be in contact with the edge of the cam 55. As the cam 55 is turned by the gear 56 and the worm gear 58, the radii of this cam increase in accordance with the curve of permissive speed, thereby tending to move the roller 48 to the right. As the roller 48 is moved to the right, unless the speed of the train is reduced correspondingly so that the arm 43 may follow the movements of the lever 46, the spring 50 will be extended and the contact stud 45 will be drawn out of electrical contact with the extension 49 of the lever 46, thereby interrupting the circuit Number Eight for energizing the electrically operated valve SB controlling the service application of the brakes. In this way, if the actual speed of the train at any movement exceeds the permissive speed allowable for it at that particular instant, the service brakes will be automatically applied.
- In the particular embodiment of the in-

vention illustrated it is contemplated that the speed of the vehicle will be automatically reduced by the cooperation of the cam and speed responsive device, in the manner already explained, until a predetermined low speed, such as 5, 8 or 10 miles per hour, has been reached, whereupon this predetermined low speed limitation will be maintained until the speed control apparatus is re-set or restored. This provision enables a vehicle, after having its speed reduced to the predetermined minimum while traveling through a block, to continue its movement and enter the next block, if the circumstances render it expedient to do so. The maximum radii of the cams 54 and 55 are selected to impose this predetermined minimum speed; and to prevent damage to the apparatus and other objectionable results, by a continued movement of the train after the cams have been moved to their extreme minimum speed position, the cut-away portion 56¹ is provided in the gear 56 so as to permit the worm 58 to rotate idly without driving the gear 56 when the shaft 51 has attained its minimum speed position.

The speed control apparatus is automatically restored upon reenergization of the control relay K. This supplies current to the cam-starter magnet 61, which raises the shaft 57 and disengages gears 56 and 58, so that the shaft 51 and its cams may return to the normal or initial position under the influence of the counterweight 56¹.

It is contemplated that suitable devices, similar to those disclosed in my prior application, Serial Number 65,071, filed December 4th, 1915, will be provided whereby the engineer or motorman will be given a suitable warning signal a sufficient time before the automatic application of the brakes occurs to permit him to apply the brakes himself. When such a warning signal is used it is practical to hold the engineer or motorman strictly accountable for any automatic application of the brakes which may occur since he is informed by the lighting of the yellow lamp that he should proceed cautiously and is further advised by the warning signal when he should immediately commence to reduce the speed of his train. With the aid of the illustration and description in my prior application above mentioned, the addition or application of the warning signal to the parts of the system shown and described is considered to be within the ability of one skilled in the art of railway signaling; and to avoid confusion and complication this warning signal has not been shown.

Maximum permissive speed.

In the system embodying this invention, provision is made to prevent automatically the train from attaining a speed greater than a maximum permissive speed, even

though there may be a clear track ahead of the train. Referring to Fig. 2, it can be seen that even though the cam 55 is stationary in its normal position, the speed 5 arm 46 cannot be moved to the left through more than a certain angle without causing separation of the arm 49 from contact stud 45 of the corresponding arm 43, since the roller 48 of the speed arm 46, after this 10 arm has moved through a certain angle counterclockwise, strikes the edge of the corresponding cam 55. In other words, when the cam 55 is in its normal position, the actual speed of the train cannot exceed a certain amount without causing an automatic 15 application of the brakes in the same way as occurs when the actual speed of the train exceeds its permissive speed. The same effect is produced if the speed of the train is being 20 controlled by the cam 54. It should be noted that the cams 54 and 55, correspond to blocks of different lengths having different curves of permissive speed, and are in practice shaped differently so as to impose different 25 limitations upon the maximum speed which the train may attain when traveling under a proceed signal with a clear track ahead. In the particular construction illustrated, this result is accomplished by making the 30 radius of one cam, namely, the cam 54, to the point marked α greater than the corresponding radius of the other cam 55, so that the arm 47, which is assumed to be in the same plane with the arm 46, cannot move counterclockwise as far as the arm 46 can move 35 before the roller 48 strikes the edge of the cam 54; but obviously the same result may be obtained in other ways.

By reason of the features of the construction just described, the train in any one block cannot attain a speed greater than the maximum permissive speed prescribed for it by the cam corresponding to that block. This limitation upon the maximum speed 40 which the train may attain in the block while traveling under a proceed signal not only makes it possible to restrict the speed of a train in any given portion of the track to a speed proper to safety, but also makes 45 it practicable to regulate the speed of a train in any one block so that the train, when it leaves that block and enters the next block, cannot be traveling so fast that its speed 50 cannot be safely governed in this next block. 55 To illustrate, referring to Fig. 1, a train in the block A cannot attain a speed greater than the speed indicated by the line 7. Consequently the speed of the train when it 60 enters the block B cannot be greater than the maximum permissive speed for the block B, so that the speed of the train may be reduced in accordance with the curve of permissive speed for the block B by the time the train reaches the end of the block C, if the traffic 65 conditions require such a reduction in speed.

The same safety is obtained where the block having a low maximum permissive speed is followed by a block having a high maximum permissive speed, since it is apparent that when the train leaves the first block and 70 enters the second block, it must necessarily be traveling at a speed less than the maximum permissive speed of the second block. Such a condition is indicated in Fig. 1, where the block E is followed by the blocks 75 F and G, the maximum permissive speed for the block E being lower than that for the combined blocks F and G. In practice it is probable that a train after leaving the block E would accelerate as indicated by the dotted line designated 200. The same principle does not hold true, however, where a block having a high maximum permissive speed is followed by a block having a lower maximum permissive speed. Such a case 80 is illustrated in Fig. 1 where the combined blocks B and C are succeeded by the shorter block D having a lower maximum permissive speed; and from Fig. 1 it can be seen that if a train in the combined blocks B and C were 85 allowed to continue at the maximum permissive speed indicated by the line 7, this train might enter the block D at such a high speed that even though the brakes were 90 immediately applied, it could not be brought 95 to a stop or to a predetermined low speed by the time it reached the end of the block D. For this reason it is not permissible to permit a train to maintain the same maximum 100 permissive speed throughout the lengths of 100 the blocks B and C; but on the contrary it is necessary to compel the train to reduce its speed in the block C so that when it enters the block D, it will not be traveling at a 105 speed greater than the maximum permissive speed of the block D. Moreover, this reduction of speed in the block C should occur regardless of whether the train is traveling under the proceed signal or caution signal. The reduction of speed in the block C is 110 accomplished automatically by setting the safety control apparatus into operation upon each train every time it enters the block C so that the train is compelled to follow the curve of permissive speed indicated in Fig. 1 115 for the block C, which, as can be seen from the curves in Fig. 1, intersects the vertical line d at a point indicating substantially the same speed as the maximum permissive speed of the block D. 120

Trackway circuits.

The operation of the parts of the system carried on the train having been generally described, and the different effects produced on this apparatus by potential differences of different intensities between the successive ramps passed by the train having been set forth, it is now possible to consider the arrangement of the trackway circuits shown in 125 130

5 Figs. 3 and 4 whereby the voltages supplied to the different ramps are controlled in accordance with the traffic conditions so as to produce the proper controlling effects on the train. In giving this description of the trackway circuits, is considered sufficient, in view of the foregoing description, to merely trace the different circuits set up along the track under different traffic conditions, and state briefly the action produced on the speed control apparatus on the train.

10 Referring to Fig. 3, assume that a train is approaching the entrance to the block A, and that no dangerous conditions exist in either the blocks A, B or C. Under these conditions the track relays 9, 9¹ and 9² of the respective blocks A, B and C are energized, and their respective armatures are in their upper position as shown in Fig. 3. As the 15 train in question proceeds and the first contact shoe carried thereby engages the ramp RA, the parts of the speed control apparatus are restored to their normal position, if they are not already there, and are held 20 in their normal position, by reason of the high difference of potential existing between the ramp RA and the track rail 1, due to the 25 following partial circuit:

30 Commencing at the ramp RA, conductor 166, armature 10 of the track relay 9 in its upper position, conductor 167, batteries 14, 15 and 16 in series, and conductor 168, back to the track rail 1.

35 As the train in question progresses and its first pair of wheels and axle enter the block A, the track relay 9 is shunted and its armature drops. The partial circuit for the ramp RA is then along conductor 166, armature 10 of the track relay 9 in its lower position, 40 along the conductor 169 leading ahead to the armature 11¹ of the track relay 9¹ in its upper position, thence along conductor 170, armature 12² of the track relay 9² in its upper position, conductor 171 through the 45 batteries 14² and 15² in series, and conductor 177 to the track rail 1.

50 Thus if neither of the blocks B nor C is occupied, a medium difference of potential will be established between the ramp RA and the track rail 1, and as explained hereinbefore this medium difference of potential is sufficient to hold the parts of the speed control apparatus in their normal position, thereby permitting the train in question 55 to pass through the block A unrestrained by the speed control apparatus, except for the limitation imposed upon the maximum speed which it may attain.

60 Suppose, however, that when the first mentioned train enters the block A, that another train occupies the block B. Under this condition, the track relay 9¹ is deenergized and its armature 11¹ is in its lower position and connects the ramp RA to a

65 low voltage source of current by the partial circuit as follows:

Commencing at the ramp RA, conductor 166, armature 10 of the track relay 9 in its lower position, conductor 169, armature 11¹ of the track relay 9¹ in its lower position, conductor 172, battery 14¹ and conductor 173 to the track rail 1.

70 This low difference of potential, while it maintains the stop relay S sufficiently energized to hold its armatures in their upper 75 position, results in the dropping of the armatures of the control relay K, so as to change the proceed signal to the caution signal and set the cam 55, corresponding to the block A, into motion so as to compel a reduction in the speed of the first mentioned train corresponding to the curve of permissive speed for the block A. It is contemplated that the motorman or the engineer of the train, aided possibly by some other 80 means, such as the warning signal hereinbefore referred to, will ordinarily obey the caution signal and control the speed of his train in the block A so that an automatic application of the brakes is necessary; 85 but it is apparent that if the motorman or the engineer fails for any reason to perform his duty the speed of the train will be controlled automatically. While it is possible by properly shaping the cam 55 to bring 90 the train to a complete stop by the time it reaches the end of the block A, the particular embodiment of the invention illustrated is designed with a view of bringing the train to a certain predetermined low 95 speed at the end of the block A for the reason that practical operating requirements seem to be satisfied without bringing the train to a complete stop.

100 For the next illustration, assume that when the train first referred to enters the block A, the block C is occupied by another train. Under these conditions the armature 12² of the track relay 9², being in its lower position connects the ramp RA with the 105 battery 14²; and by reason of this low difference of potential between the ramp RA and the track rail 1, the speed control apparatus is set into operation.

110 It should be noted that the combined length of the blocks B and C is assumed to be substantially equal to the length of the block A; or, in other words, the curves of permissive speed are the same for the blocks B and C taken together as for the block A alone (see Fig. 1). For this reason it is necessary to make the partial circuit establishing a medium difference of potential between the ramp RA and the track rail 1 dependent upon both of the track relays 9¹ and 9². This condition, in which the controlling circuit for the ramp is controlled 120 by the track relays of the two blocks in ad-

vance, should not be confused with the so called overlap control, but is necessary in order to provide braking distance between successive control points. Further illustrations of this condition appear in connection with the control of the ramps for the blocks F, G, H and I.

Referring again to the progress of a train through the block A, as a further illustration, assume that when the first mentioned train entered the block A, the block C was occupied by another train; but that by the time the first mentioned train reaches the end of the block A, the other train formerly in the block C has entirely moved into block D. By the time the first mentioned train reaches the entrance of the block B and its first contact shoe engages the ramp RB, it will be traveling at the predetermined low speed hereinbefore described; but since neither of the blocks B nor C is occupied, that is, there is a full braking distance between the first mentioned train and the next train in advance, it is permissible for the first mentioned train to accelerate and move through the blocks B and C as fast as the curve of permissive speed for these blocks allows. In the system embodying this invention, this result is accomplished by releasing or restoring the parts of the speed control system to their normal position at the ramp RB, this being attained by establishing a high difference of potential between the ramp RB and the track rail 1 by a partial circuit as follows:

Commencing at the ramp RB, conductor 178, armature 10¹ of the track relay 9¹ in its upper position, conductor 179, armature 10² of the track relay 9² in its upper position, conductor 180, batteries 14², 15² and 16² in series, and conductor 177 to the track rail 1.

After the first mentioned train actually enters the block B, the difference of potential between the ramp RB and the track rail 1 is dependent upon the condition of the block in advance, as the block D. If the block D is not occupied by a train, the armature 11² of the track relay 9² is in its upper position, and connects both of the batteries 14² and 15² by conductors 178, 181, 182 and 183 to the ramp RB, thus establishing a medium difference of potential between the ramp RB and the track rail 1. However, if the block D is occupied by another train, the armature 11² of the track relay 9² is in its lower position, and connects the ramp RB by conductor 185 to the battery 14² alone, thus establishing a low difference of potential between the ramp RB and the track rail 1. In this way, if the block D is occupied, the speed control apparatus of the first mentioned train entering the block B is set into operation; whereas if the block D is not occupied the speed con-

trol apparatus of the first mentioned train 65 remains in its normal position.

Change from long block to short block.

Referring to Fig. 1, it can be seen that the block D is shorter than the combined 70 lengths of the blocks B and C, and that the maximum permissive speed of the block D is lower than that for the blocks B and C; and, as explained hereinbefore, it is necessary to provide some way of setting the 75 speed control apparatus on a train passing through the blocks B and C into operation at some intermediate point, this point being in this particular instance at the entrance of the block C. In fact, it may be 80 said that the length of the block C is determined with reference to the maximum permissive speeds of the block D and of the blocks B and C, so that if the speed control apparatus on a train traveling at the maximum permissive speed in the block B is set 85 into operation at the entrance to the block C, the speed of this train at the entrance to the block D will not exceed the maximum permissive speed for the block D. In order 90 that the speed control apparatus may be set into operation on each train when it enters the block C, the ramp RC is directly connected by means of conductors 186, 174 and 175 to the battery 14²; or, in other 95 words, a low difference of potential exists at all times between the ramp RC and the track rail 1 regardless of traffic conditions. In this connection it should be noted that it 100 is necessary to have a low difference of potential between the ramp RC and the track rail 1 in order to prevent the emergency application of the brakes; and in systems where the emergency application of the 105 brakes is dispensed with, as shown in Fig. 105 5, or in cases where the emergency application is produced in some other way, it is possible to have the ramp RC totally disconnected from any source of current, as 110 shown in Fig. 6.

Control for fixed hazards.

Referring to the part of the track including the blocks D and E, this arrangement is assumed in order to illustrate the 115 control of the speed of a train on the approach to, or by a fixed hazard, as sharp curves. The sharp curves in the blocks D and E make it desirable to require that the permissive speed which a train may attain 120 in these blocks should be comparatively low; and since the braking distance for a train traveling at a low speed is less than that of a train travelling at a high speed, it is possible to make the blocks D and E shorter 125 than the block A, so that trains travelling at a low speed in the blocks D and E may approach closer to each other. It is noted

here that the conditions just explained illustrate one necessity for having the blocks of a railroad of different lengths. According to this invention allowance is made for 5 the comparative low maximum permissive speed for the blocks D and E for the shorter length of these blocks by using a cam, as the cam 54, which is shaped differently than the cam 55 for the longer block, as the block 10 A, and by making the speed control apparatus on the train subject to the cam 54 instead of the cam 55. This change is effected by the selector mechanism and the selector tappets or shoes 74, 75 and 76, which are 15 actuated by the selector ramps SR, SC and SL. In the particular arrangement shown, the selector tappet 74, which is actuated by the right hand selector ramp SR controls the selection of the cam 54; whereas the selector 20 tappet 76 actuated by the left hand selector ramp SL, controls the selection of the cam 55. While a train is traveling through the blocks A, B and C, the cam 55 on that train is effective, and the selector 25 relay 81 controlling that cam is maintained energized by the middle selector tappet 75. Near the entrance to the block D are arranged a middle selector ramp SC and a right hand selector ramp SR; and when a 30 train passes these selector ramps the selector tappets 74 and 75 are raised. The raising of the middle selector tappet 75 interrupts circuit Number Seven which maintains the selector relay 81 energized, and since the selector 35 tappet 76 is in its lower position and the circuit Number Six is interrupted, the selector relay 81 is deenergized and its armatures drop. At the same time the raising of the selector tappet 74 closes circuit 40 Number Nine and energizes the selector relay 80. The right hand selector ramp SR is made longer than the middle selector ramp SC, as shown in Figs. 1 and 3, so that before the selector tappet 74 returns to its 45 normal lower position and interrupts the circuit Number Nine, the middle selector tappet 75 leaves engagement with the middle selector ramp SC and in returning it to its normal position closes the circuit Number 50 Ten which maintains the selector relay 80 energized. While the selector relay 81 is energized, the electrically operated valve SB, controlling the service application of the breaks, is controlled by the cam 55 through 55 circuit Number Eight; but while the selector relay 80 is energized, said valve SB is controlled by the cam 54 through circuit Number Eleven. As explained hereinbefore, the cam 54 is shaped to compel the train to keep 60 below a maximum permissive speed which is lower than the maximum permissive speed for the block A; and the cam 54 remains effective to control the speed of the train until the train reaches the selector ramps 65 SC and SL located near the end of the

block E, whereupon the middle selector ramp SC raises the middle selector tappet 75 and interrupts the circuit Number Ten, the left hand selector ramp SL at the same time raising the selector tappet 76 to close the 70 circuit Number Six, so that when the selector tappet 75 returns to its lower position, it closes circuit Number Seven and maintains the selector relay 81 energized. In this way 75 the control of the speed of a train is shifted from the cam 54 back again to the cam 55.

For the control of a train by fixed hazards as around sharp curves and the like, it is desirable that the train should not be allowed to accelerate until the last car there- 80 of has completely passed the fixed hazard. These advantageous results may be easily obtained according to this invention providing a train is equipped with a locomotive or motor car at each end, each of said locomotives or motor cars being equipped with a speed control apparatus, since the speed of the train as a whole cannot be increased until the last locomotive or motor car has passed the selector ramps SC and SL at the entrance to the block F, and until the train has wholly passed the fixed hazard its speed will be kept below the maximum permissive speed imposed by the cam corresponding to 85 the blocks adjacent to the set fixed hazard. Similar results may be accomplished in the case of a train having a locomotive or motor car at the front end only by locating the selector ramps SR and SC a train length ahead of the end of the block E, that is, a train length ahead of the forward limit of the zone of fixed hazard; but this arrangement has the disadvantage that all trains to travel over a railroad are not of the same 90 length so that a short train will be unnecessarily delayed and a long train will be allowed to accelerate too quickly. 95

Referring to the controlling circuits for the ramp RD, assume that neither of the blocks D nor E is occupied. Under these 100 conditions until a train enters the block D a high difference of potential exists between the ramp RD and the track rail 1 according to a partial circuit as follows: 105

Commencing at ramp RD, conductor 187, 110 armature 10³ of the track relay 9³ in its upper position, conductor 188, batteries 14³, 15³ and 16³ in series, and conductor 184 to the track rail 1. 115

When the train actually enters the block D, the track relay 9³ is shunted and deenergized, and remembering that it is assumed that the block E is not occupied, a medium difference of potential, which keeps the parts of the speed control apparatus in their 120 normal position, is established between the ramp RD and the track rail 1 by a partial circuit, as follows: 125

Commencing at the ramp RD, conductor 187, armature 10³ of the track relay 9³ in its 130

lower position, conductor 189, armature 11⁴ of the track relay 9⁴ in its upper position, conductor 190, batteries 14⁴ and 15⁴ in series, and conductor 191 to the track rail 1.

5 If, however, the block E is occupied at the time a train enters the block D, only a low difference of potential, which will cause the parts of the speed control apparatus to be set into operation, is established between 10 the ramp RD and the track rail 1, since the armature 11⁴ is in its lower position and contacts with conductor 192 connecting to the battery 14⁴ alone. In this way, the parts of 15 the speed control apparatus are properly controlled when a train enters the block D according to traffic conditions in the block D and the next block E in advance, the parts being restored to their normal position, and held in their normal position, or 20 set into operation, according to the traffic conditions in the block E in the same way as hereinbefore described for a train entering the block A.

25 *Control at stations, crossings and the like.*

The blocks F, G, H and I illustrate an arrangement which is desirable adjacent to a station stop, or the like, and also an arrangement whereby a train approaching 30 switches and signals controlled by an interlocking plant, is given the proper warning signal, is compelled to reduce its speed if necessary and is brought to an absolute stop in case an attempt is made to pass the 35 signal when said signal is indicating stop or danger. The track switch between the stretch of track T³ and the stretch of track T² and the signals M and N controlling the 40 traffic over the stretches of track T² and T³ respectively, are controlled by an interlocking machine in the tower W in a usual or suitable manner, which, in order to avoid 45 confusion, is not illustrated. In addition to controlling the track switch and signals N and M from the tower W, it is necessary to 50 control certain ramps on the stretches T² and T³, but since the control for the ramps on the stretch T³ is similar to the control for the ramps in stretch T², this control is illustrated 55 for the ramps along the stretch T² only. The control of the ramps for giving the caution signal to a train approaching the signal M at danger and for compelling a train to come to an absolute stop if it 60 attempts to pass the signal M at danger is obtained by a suitable circuit controlling device O, which is operated in connection with the control of the signal M in any suitable way, and which for simplicity is shown 65 diagrammatically in Fig. 4 as comprising a rod 216, assumed to be of insulating material, which operates switches 217, 218, 219 and 220 adapted to make electrical connection with suitable contacts indicated by arrows. The switches 217, 218, 219 and 220

are shown in Fig. 4 in their position corresponding to the condition existing when the signal M indicates proceed, it being understood that the signal N in this case indicates stop.

70

Speed control through interlocking territory.

Disregarding for the moment the operation of the system whereby a train is 75 brought to an absolute stop if it attempts to pass the signal M at danger, assume a train in the block D about to enter the block E, and that neither the blocks E, F nor G is occupied by another train. Before 80 the first mentioned train enters the block E, a high difference of potential, which is capable of restoring the parts of the speed control apparatus to their normal position or to hold them in their normal position, 85 is established between the ramp RE and the track rail 1 by a partial circuit, as follows:

Commencing at the ramp RE, conductor 193, armature 10⁴ of the track relay 9⁴ in its 90 upper position, conductor 194, batteries 14⁴, 15⁴ and 16⁴ in series, and conductor 191 to the track rail 1.

When the first mentioned train enters 95 the block E, the armature 10⁴ of the track relay 9⁴ drops, and remembering that it is assumed that the blocks F and G are not occupied, a medium difference of potential, capable of maintaining the control relay K 100 energized, is established between the ramp RE and the track rail 1 by a partial circuit, as follows:

Commencing at the ramp RE, conductor 193, armature 10⁴ of the track relay 9⁴ in its 105 lower position, conductor 195, armature 11⁵ of the track relay 9⁵ in its upper position, conductor 196, armature 13⁶ of the track relay 9⁶ in its upper position, conductor 197, batteries 14⁶ and 15⁶ in series, and conductor 198 to the track rail 1.

In case it happens that the block F is occupied by a train, the armature 11⁶ of the track relay 9⁶ is in its lower position so 115 that conductor 195 is connected through conductor 199 to battery 14⁵, and thence by conductor 201 to the track rail 1, thereby establishing only a low difference of potential between the ramp RE and the track rail 1, which results in the speed control 120 apparatus being set into operation. In a similar way, if the block G is occupied, although the block F is not occupied, the armature 13⁶ of the track relay 9⁶ in its lower position will connect the conductor 196 connecting with the ramp RE to the battery 14⁶ by conductors 202 and 203 and thence by conductor 198 to the track rail 1, thereby establishing a low difference of potential 125 between the ramp RE and the track rail 1, which causes the speed control appa- 130

ratus on the first mentioned train to be set into operation.

Assume that the first mentioned train passes through the block E and is about to enter the block F. Then, before the train actually enters the block F, a high difference of potential is established between the ramp RF and the track rail 1 by a partial circuit which can be easily traced by analogy to the 10 partial circuit for the ramp RA which is set up before a train enters the block A. Also when the first mentioned train actually enters the block F, a medium difference of potential is established between the ramp RF 15 and the track rail 1, providing neither the block G nor the block H is occupied by another train, by a partial circuit which can be easily traced by analogy to the partial circuit set up for the ramp A, under like 20 conditions. Likewise, if the block H is occupied by a train, only a low difference of potential will exist between the ramp RF and the track rail 1, so that the speed control apparatus on the train entering the block F 25 is set into operation.

It is noted that in the arrangement of controlling circuits shown in Fig. 4, if the block G is occupied when a train enters the block F, a low difference of potential is 30 established between the ramp RF and the track rail 1. This low difference of potential merely serves to keep the ramp RF sufficiently energized so as to prevent an emergency application of the brakes and does not 35 enter into the control of the speed control apparatus, for the reason that a train now assumed to be in the block G, must have been either in the block F or G at the time the following train entered the block E, so that the speed control apparatus on said following 40 train has already been set into operation by the time this train reaches the entrance to the block F.

The partial circuit for establishing a high 45 difference of potential between a ramp RG and a track rail 1 is like the corresponding circuit associated with the ramp RF and in the same manner as described in connection with the control of the ramp RF, a train in 50 the block F and about to enter the block G will have the parts of its speed control apparatus either restored to their normal position or held in their normal position, providing that neither the block G nor the block H is occupied. When this train 55 in the block F actually enters the block G, and the armature 10⁶ of the track relay 9⁷ drops, a medium difference of potential is established between the ramp RG and the track rail 1, providing neither the block H nor the block I is occupied, by a 60 partial circuit as follows:

Commencing at the ramp RG, conductor 65 206, armature 10⁶ of the track relay 9⁷ in its lower position, conductor 207, armature 12⁷

of the track relay 9⁷ in its upper position, conductor 208, switch 218, conductor 209, armature 13⁸ of the track relay 9⁸ in its upper position, conductor 210, batteries 14⁸ and 15⁸ in series, and conductor 211, back 70 to the track rail 1.

If at the time a train enters the block G the block I is occupied, the armature 13⁸ of the track relay 9⁸ will be in its lower position and will connect the conductor 209 leading 75 to the ramp RG to the battery 14⁸ alone by means of conductors 212 and 213, so that only a low difference of potential will exist between the ramp RG and the track rail D, the partial circuit for establishing this low 80 difference of potential being the same as the circuit last traced as far as the armature 13⁸. For the same reason as explained hereinbefore in connection with the movement of a train into the block F, a train entering the 85 block G when another train occupies the block H, will have had its speed control apparatus already set into operation and, finding only a low difference of potential between the ramp RG and the track rail 1, will have to 90 continue under the dominance of its speed control apparatus since this low difference of potential is insufficient to restore the parts of the speed control apparatus to their normal position, although it is sufficient to prevent the automatic emergency application of the brakes. 95

Assume that the train under consideration is in the block G and about to enter the block H; and that neither of the blocks H nor I is occupied. Under these conditions a high difference of potential exists between the ramp RH and the track rail 1 because of a partial circuit analogous to the partial circuit hereinbefore traced for the ramp RG, except that this partial circuit for the ramp RH is controlled by the switch 217, said 100 partial circuit for the ramp RH being as 105 follows:

Commencing at the ramp RH, conductor 110 214, armature 10⁷ of the track relay 9⁷ in its upper position, conductor 215, switch 217 in the position shown, conductor 221, armature 11⁸ of the track relay 9⁸, conductor 222, batteries 14⁸, 15⁸ and 16⁸ in series and conductor 221 to the track rail 1. 115

When the train in the block G actually enters the block H, a medium difference of potential exists between the ramp RH and the track rail 1, remembering that the blocks I and J are assumed to be unoccupied, because of a partial circuit as follows:

Commencing at the ramp RH, conductor 120 214, armature 10⁷ of the track relay 9⁷ in its lower position, conductor 223, armature 12⁸ of the track relay 9⁸ in its upper position, conductor 224, armature 13⁹ of the track relay 9⁹ in its upper position, conductor 225, batteries 14⁹ and 15⁹ in series and conductors 125 226 and 227 to the track rail 1. 130

If at the time the first mentioned train actually enters the block H, the block J is occupied by another train, the armature 13° of the track relay 9° will be in its lower position and will connect the conductor 224 to the battery 14° alone along conductors 230 and 231, thereby establishing only a low difference of potential between the ramp RH and the track rail 1. If the block I is occupied at the time the first mentioned train enters the block H, no effect is produced upon the speed control apparatus for the reasons hereinbefore explained in connection with the movement of the train into the block F when the block G is occupied.

Considering the progress of the train further assume that it now occupies the block H and is about to enter the block I; and that neither of the blocks I nor J is occupied. It can be seen from Fig. 4 that the ramp RI at the entrance to the block I is shown differently from the other ramps and is preferably made of two parts insulated from each other, said parts being designated RI¹ and RI². This ramp RI at the entrance to the block I may consist of two separate ramps having their adjacent ends slightly separated, or may consist of a continuous ramp having suitable insulating material inserted therein between its ends. In either case the insulation or the break which divides this ramp into two parts is preferably so placed that the locomotive or the first motor car of a train may move up until its front end is opposite the signal M without any of the contact shoes carried thereby touching the part RI²; and it is further so placed that if the train passes by the signal M, its first contact shoe will engage the part RI². When the signal M indicates proceed the two parts RI¹ and RI² of the ramp RF are electrically connected by conductors 232, switch 219 in the position shown, conductors 233 and 238, switch 220 in the position shown and conductor 237, so as to constitute in effect one continuous ramp. Assuming that the signal M indicates proceed and the switches 219 and 220 are in the position shown, when neither the block I nor the block J is occupied, a high difference of potential exists between both parts RI¹ and RI² of the ramp RI and the track rail 1 because of a partial circuit as follows:

Commencing at the part RI¹, conductor 232, switch 219 in the position shown, conductors 233 and 234, armature 10° of the track relay 9° in its upper position, conductor 235, armature 11° of the track relay 9° in its upper position, conductor 236, batteries 14°, 15° and 16° in series and conductors 226 and 227 to the track rail 1.

When a train actually enters the block I, the armature 10° of the track relay 9° drops and the control of the ramp RI at the entrance of the block I is taken from the block

ahead of the block J so that if this block ahead is occupied, the speed control apparatus on the train as it enters the block I will be set into operation.

Station stops.

Without attempting to explain all of the conditions and circumstances where the overlapping controls illustrated in connection with the blocks F to J inclusive find useful application in facilitating the movement of traffic, one application of this arrangement of circuits is illustrated by assuming that a station is located at some point in this portion of track including the blocks F to J inclusive, as for instance, opposite the block H. Assume that two trains following each other are approaching this station. There is nothing to determine for all cases just how far apart the trains will be traveling, or how long the first train may stop at the station; and it may well happen that while the first train is stopping at the station the second train will enter the block F. Since the first train at the station occupies the block H, only a low difference of potential exists between the ramp RF and the track rail 1 and this low difference of potential as explained hereinbefore, will set the speed control apparatus on the second or following train into operation. While the second train is reducing its speed and is passing through part of the distance to the station, suppose that the first train pulls out of the station and gets entirely into the block I; then, under these circumstances it would be unnecessary to compel the second train to continue to reduce its speed, but on the other hand it would be proper to release the following train from the dominance of its speed control apparatus and permit it to proceed and delay the application of its brakes until necessary to bring it to a stop opposite the station. This release of the speed control apparatus on the following train is accomplished by the ramp RG which will have a high difference of potential between it and the track rail 1, since neither of the blocks G nor H is occupied. Obviously other intermediate release ramps like the ramp RG may be located between the ramp RF and the ramp RG if desired.

Absolute stop.

As pointed out hereinbefore it is desirable to make provision for bringing a train to an absolute stop at certain places where there are converging or intersecting tracks, and such a case is illustrated in Fig. 1, where it is necessary to provide for bringing a train to an absolute stop when the track switch connecting the portion of the track T³ with portion of the track T² is set for the train to move from said portion T³ to the portion T², and when the signal M indicates stop.

Also, a train approaching the signal M at stop should receive a caution signal at braking distance back from the signal M, that is, at the ramp RG. Also, a train should be 5 allowed to pull up to signal M, when said signal is indicating stop, without interference, but the train should be immediately stopped if it attempts to pass beyond the signal M at stop. Furthermore, it is desirable 10 to obtain the above mentioned caution signal and an absolute stop by means of the same ramps which are used for controlling the speed of a train through successive blocks.

15 These results, together with other apparent advantages, are accomplished by the circuit controlling device O, the rod 216 being shifted from the position shown in Fig. 4 to its other position, so that 20 when a train enters the block G only a low difference of potential will exist between the ramp RG and the track rail 1 by reason of the fact that the switch 218 is shifted to connect the conductor 208 to the battery 14^s 25 alone along conductors 240, 241 and 242. In a similar way a low difference of potential exists between the ramps RH and the track rail 1 by reason of the fact that the switch 217 is shifted to connect 215 to the 30 battery 14^s alone by means of the conductors 243, 241 and 242. Consequently, when a train enters the block G, its speed control apparatus is set into operation and continues in operation after the train passes the 35 ramp RH, since a low difference of potential exists between the ramp RH and the track rail 1 before the train enters the block H and either a low or medium difference of potential exists between the ramp RH and the 40 track rail 1 after the train enters the block H dependent upon the traffic conditions in the blocks I and J. The part RI¹ of the ramp RI is connected to the low voltage battery 14^s along conductor 232, switch 219 45 shifted, conductors 244 and 242; and consequently a train may pull up to signal M without having its stop relay S deenergized by the engagement of its contact shoe with the part RI¹. The part RI² of the ramp RI 50 is directly shunted or short circuited to the track rail 1 by means of conductor 237, switch 220 in its shifted position and conductors 245 and 227. Consequently there is 55 no difference of potential between the part RI² of the ramp, RI, so that if a train attempts to pass the signal M at stop, the contact shoe of this train engages the part RI², and since there is no difference of potential 60 between this part RI² and the track rail 1, the stop relay S will be deenergized and its armature 90 will drop to interrupt the circuit number five which normally energizes the electrically operated valve EB, the result being an automatic emergency application 65 of the brakes. In the particular ar-

rangement of the circuits illustrated not only is the part RI² of the ramp RI disconnected from any source of current, but is also shunted to the track rail 1. The purpose of this low resistance connection between the 70 part RI² of the ramp RI and the track rail 1 is to prevent a low difference of potential between the ramp RH and the track rail 1 from preventing the emergency application of the brakes in case the train includes a 75 number of locomotives or motor cars each equipped with contact shoes connected electrically in some manner to obtain simultaneous operation and in case such a train is longer than the block H, so that while the 80 contact shoe on the first locomotive or motor car engages the ramp RI, another contact shoe engages the ramp RH. Under the circumstances just described, it will be apparent that without the special provision of the 85 low resistance connection between the ramp RI² and the track rail 1, current will be supplied from the ramp RH to the bus line or other means connecting the separate locomotives or motor cars in the train so as to 90 maintain the stop relays S on the several locomotives or motor cars energized regardless of the fact that there is no difference of potential between the head part RI² of the ramp RI and the track rail 1. With 95 this low resistance path from the head part RI² of the ramp RI and the track rail 1, however, current, if supplied to the bus line on the train through the ramp RH, would 100 flow through this low resistance path to the track rail rather than through the stop relays S on the train to the track rail.

The broad combination and arrangement of parts and circuits adapted to cause preliminary reduction in speed of the train and an absolute stop at interlocked signals and similar control points along the track, as described herein, is claimed in my co-pending application, Ser. No. 88,365, filed the same day; and the claims herein are limited 105 to specific features not disclosed in my other application.

While the automatic train control system embodying this invention has been shown and described as designed to be operated by direct current, simple modifications, which will be apparent to those skilled in the art of railway signaling, may be made whereby alternating current may be advantageously used as an operating medium. Also, although one of the track rails, namely, track rail 2, is shown as divided into blocks by the insulating joints 3, both track rails may be divided into blocks if desired; and in cases 115 where it is desirable to use the track rails as a return for propulsion current, this result may be easily attained by the use of impedance bonds and other devices well known to those skilled in the art. Various other 120 modifications may be made in the particular 125

construction of parts and arrangement of the control circuits shown and described without departing from the invention and without modifying or changing the functions of these parts and their operation; and also, various features may be combined with this system without departing from the invention, as for instance several locomotives or motor cars each equipped with a train control apparatus which may be included in a train.

Although I have particularly described the construction of one physical embodiment of my invention, and explained the operation and principle thereof; nevertheless I desire to have it understood that the form selected is merely illustrative, but does not exhaust the possible physical embodiments of the idea of means underlying my invention.

What I claim as new and desire to secure by Letters Patent of the United States, is:

1. In a system for automatically protecting railway traffic, in combination; a stretch of track divided into two blocks of different lengths, the shorter block being in advance of the longer block; a vehicle adapted to move over said stretch of track; means adapted to establish in its initial condition the maximum permissive speed for said vehicle in each of said blocks; said means being adapted when set into operation to establish a decreasing permissive speed for each of said blocks; means on the vehicle for establishing the actual speed thereof; traffic protecting means on the vehicle responsive to a predetermined interaction between said first mentioned means and said last mentioned means and operated when the actual speed of the vehicle at a point in its travel exceeds its permissive speed for that point; and devices carried by the vehicle and located along the track in cooperative relation for setting said first mentioned means into operation at a predetermined point in the longer block, whereby the actual speed of the vehicle as it enters the shorter block will not exceed the maximum permissive speed for that shorter block.

2. In a system for automatically protecting railway traffic, in combination; a stretch of track divided into blocks; a vehicle adapted to travel over said stretch; devices for establishing different maximum permissive speeds for said vehicle in said blocks and adapted when set into operation to impose gradually decreasing permissive speeds; means for establishing the actual speed of the vehicle; traffic protecting mechanism on the vehicle responsive to a predetermined cooperation of one of said devices and said means and operated when the actual speed of the vehicle exceeds the permissive speed prescribed by the correspond-

ing device; means on the vehicle arranged in cooperative relation with means located along the track for selecting the device effective to govern said traffic protecting mechanism; and means for initiating the operation of one of said permissive speed devices at a distance in the rear of each point of change to a lower maximum permissive speed.

3. In a system for automatically protecting railway traffic, in combination; a stretch of track divided into track circuit blocks some of which are divided into track sections; a vehicle adapted to travel over said stretch of track; traffic protecting mechanism on the vehicle; means located at the entrance of each block and governed by the track circuit of the next block in advance for rendering said mechanism effective when said block in advance is occupied; and means located at a track section between the ends of each block and governed by the track circuit of the next block in advance for restoring said mechanism to its idle condition when said next block in advance is not occupied.

4. In a system for automatically protecting railway traffic, in combination; a stretch of track divided into track circuit blocks; a vehicle adapted to travel over said stretch of track; train control mechanism on the vehicle for bringing it to an absolute stop; traffic protecting apparatus on the vehicle; control means on the vehicle for governing said train control mechanism and said traffic protecting apparatus; a trackway impulse device associated with each block and adapted to influence the control means on the vehicle, said impulse device for each block being governed by the track circuit in the next block in advance and operating to set said apparatus in operation when said next block in advance is occupied; the impulse device associated with a predetermined one of said blocks being also capable of being placed in another distinctive controlling condition to cooperate with said control means on the vehicle to set said absolute stop mechanism into operation, and means for placing said impulse device associated with said predetermined block into said distinctive controlling condition to set said mechanism into operation and for simultaneously placing the impulse device associated with the block in the rear of said predetermined block in condition to set said traffic protecting apparatus into operation.

5. In a system for automatically protecting railway traffic, in combination; a stretch of track divided into track circuit blocks; a vehicle adapted to travel over said stretch of track; apparatus for imposing a gradually decreasing limitation on the speed of the vehicle; mechanism on the

vehicle for bringing it to an absolute stop; a contact shoe carried by said vehicle; a partial circuit for governing said mechanism and said apparatus and terminated at the wheels of said vehicle and at said contact shoe; a ramp located along the track and adapted to cooperate with said contact shoe electrically and mechanically; said mechanism being normally held in its idle condition and being set into operation when said contact shoe engages the ramp unless current is supplied from said ramp to said partial circuit; said apparatus being normally held in its idle condition and being set into operation unless current of a predetermined character is supplied from the ramp to said partial circuit; another partial circuit including sources of current of different characters associated with said ramp and controlled by the track circuit of the next block in advance; and manually operable means for breaking said another partial circuit and for simultaneously electrically connecting said ramp to a track rail by a path of low resistance.

6. In a system for automatically governing the speed of vehicles over railroad tracks divided into blocks and having regions where the vehicle should travel at relatively low speed, the combination with automatic speed control apparatus on a vehicle adapted to impose a decreasing limitation on the speed of the vehicle in accordance with its progress along the track, and means partly on the vehicle and partly along the track for initiating the operation of said apparatus at a predetermined point in the rear of the entrance to the first block of each region independently of the presence or absence of other vehicles ahead, whereby the vehicle will be automatically compelled to reduce its speed to the desired relatively low speed before entering the first block of such regions.

7. In a system for automatically governing the speed of vehicles on railroad tracks divided into blocks and having regions where trackway conditions require relatively low speeds, the combination with automatic speed control apparatus on the vehicle responsive to the speed of the vehicle and its progress along the track, of the means partly on the vehicle and partly along the track for governing said apparatus to reduce the speed of the vehicle to the desired predetermined relatively low speed prior to the entrance of the vehicle into the first block of each of such regions, said apparatus whenever thus governed imposing a continuing restriction upon the speed of the vehicle as it travels through the blocks included within the limits of such regions.

8. In a system for automatically governing the speed of vehicles over railroad tracks which are divided into blocks and which

have regions where the vehicles should travel at relatively low speeds, the combination with automatic speed control apparatus on the vehicle adapted to impose variable continuing limitations on the maximum speed of the vehicle and when set into operation to impose limitations on the speed of the vehicle which gradually decrease, of impulse devices along the track adapted to influence the operation of said apparatus, one of said impulse devices being located at the entrance to each block and having its controlling condition dependent upon the presence or absence of a train in the next block in advance, one of said impulse devices being also located at a predetermined point in the rear of each region of low speed and being permanently in a controlling condition to initiate the operation of said apparatus, whereby the vehicle will be automatically compelled to reduce its speed to the desired relatively low speed before entering the first block of such low speed regions, and cooperating elements partly on the vehicle and partly along the track for governing said apparatus to vary the maximum speed limitation imposed thereby to accord with the desired relatively low speed.

9. In a system for governing the speed of vehicles over railroad tracks divided into blocks, some of said blocks being shorter than the braking distance of the vehicle for the speed which the vehicle might attain at these points along the track, the combination with brake controlling mechanism on the vehicle, of automatic control apparatus for governing said mechanism comprising elements partly on the vehicle and partly along the track and responsive to the actual speed of the vehicle and its location along the track, said apparatus being automatically rendered active upon the approach of the vehicle to said shorter blocks to compel a reduction in the speed of the vehicle to accord with the maximum permissive speed corresponding to the length of such shorter block.

10. In a system for automatically governing the speed of vehicles on railroad tracks divided into blocks in which some of the blocks are shorter than the braking distance for the speed which the vehicle might attain at these points along the track, the combination with mechanism operable to automatically apply the brakes on the vehicle, of automatic apparatus comprising elements partly on the vehicle and partly along the track and responsive to the speed of the vehicle for causing operation of said mechanism upon the approach of the vehicle to the entrance to said shorter blocks whenever the speed of the vehicle is greater than the maximum permissive speed corresponding to the length of such shorter block.

11. In a system for automatically govern-

ing the speed of vehicles over railroad tracks divided into blocks in which some of the blocks are shorter than the braking distance for the speed which the vehicle 5 might attain at these points along the track, the combination with permissive speed means on the vehicle acting to establish gradually decreasing permissive speeds, of a speed responsive device governed by the 10 actual speed of the vehicle, brake controlling mechanism governed jointly by said speed responsive device and by said means for automatically applying the brakes when the vehicle exceeds the permissive speed es- 15 tablished by said means, and impulse trans- mitting means partly on the vehicle and partly along the track for initiating the operation of said permissive speed means upon the approach of the vehicle to said 20 shorter blocks at a predetermined point in the rear of the entrance to such shorter blocks, whereby the speed of the vehicle will be automatically reduced to accord with the maximum permissive speed correspond- 25 ing to the length of such shorter blocks.

12. In a system for automatically govern- 30 ing the speed of vehicles over railroad tracks divided into blocks, the combination with a permissive speed device adapted to im- pose predetermined maximum permissive speeds and when set into operation to im- 35 pose a gradual decreasing permissive speed, of automatic apparatus responsive to the actual speed of the vehicle and governed by said permissive speed device for auto- 40 matically applying the brakes when the ac- tual speed exceeds the permissive speed, means partly on the vehicle and partly at fixed points along the track for governing 45 said permissive speed device to cause an au- tomatic change in the maximum permissive speed established thereby to accord with the length of the blocks, and trackway impulse devices for automatically setting said per- 50 missive speed device into operation at a predeter- 55 mined point in the rear of the points where such change occurs.

13. In a system for automatically govern- 50 ing the speed of vehicles over railroad tracks in which a portion of the track is divided into track circuit sections, two or more of which are included in a space interval sufficient to enable vehicles traveling 55 over the track to be brought to a stop within the limits of such space interval, the combi- 60 nation with automatic apparatus on the vehicle operable in changing from an initial condition to an ultimate condition to impose successively lower limitations on 65 the speed of the vehicle from its maximum speed to a predetermined minimum speed during the travel of the vehicle over said space interval, impulse devices located along the track at the entrance to each track 65 section, said impulse devices being capable

of assuming distinctive resetting and oper- 70 ating controlling conditions for influencing the apparatus on the vehicle to respectively restore it to its initial condition or set it into operation, and trackway circuits con- 75 trolled by said track circuit sections for governing the controlling conditions of said impulse devices in accordance with the presence or absence of trains, the resetting controlling condition of each impulse device 80 existing when there are a sufficient number of unoccupied track sections in advance thereof to constitute said space interval, the operating conditions of each impulse device existing when the track section next in ad- 85 vance of those constituting the space inter- 90 val is occupied.

14. In a system for automatically govern- 95 ing the speed of vehicles over railroad tracks, a portion of which is divided into track circuit sections, two or more of said track circuit sections including a space interval sufficient to enable a vehicle to be brought to a stop within the limitations of such space interval, the combination with 100 automatic speed control apparatus on the vehicle having an initial condition and an ultimate condition and acting in changing from its initial condition to its ultimate condition to impose a decreasing limitation 105 upon the speed of the vehicle, and impulse devices partly on the vehicle and partly along the track controlled by the track circuits of said track sections for setting said apparatus into operation at the entrance to 110 a track section when there is no more than the space interval between that point and the next occupied track section in advance, said impulse devices exerting an influence tending to restore said apparatus to its ini- 115 tial condition at the entrance to each track section when there exists the space interval between that point and the next occupied track section in advance.

15. In a system for automatically govern- 110 ing the speed of vehicles over railroad tracks divided into blocks, some of said blocks being shorter than the braking distance of the vehicle for the speed which the vehicle might attain at such points along the track, 115 the combination with automatic speed control apparatus operable in conjunction with controlling devices along the track to establish varying maximum speed limi- 120 tations for the vehicle and to gradually re- 125 duce the speed limitations from the existing maximum as the vehicle travels along the track, controlling devices and circuits for influencing said apparatus, said controlling devices and circuits including elements act- 130 ing upon the approach of the vehicle to said shorter blocks to cause said apparatus to be set into operation, whereby the speed of the vehicle will be automatically reduced regardless of traffic conditions to a maximum

- speed corresponding to the maximum speed at which the vehicle could enter such short block and be brought to a stop within the limits of such block, said controlling devices and circuits also including means acting automatically while the vehicle is traveling through such short blocks to influence said apparatus to maintain the maximum speed limitation thus established, and means associated with each block and responsive to the presence of a train in the next block in advance for causing the operation of said speed control apparatus.
16. In a system for automatically governing the speed of vehicles over railroad tracks having a stretch of track divided into blocks of different lengths where a long block is followed by a short block, the combination with a permissive speed device on a vehicle for establishing different permissive speeds therefor, said device being adapted to be set into operation to change gradually from an initial maximum speed condition to an ultimate condition in accordance with the travel of the vehicle through the long block, of means on the vehicle for retarding the movement thereof when its actual speed exceeds the permissive speed prescribed by said device, and impulse devices along the track for influencing the operation of said permissive speed device, such an impulse device being located in the long block a distance substantially equivalent to the length of the long block from the exit end of the following short block, and which always tends to set said permissive speed device into operation, another impulse device being located at the entrance to the short block which acts to continue the operation of said permissive speed device when the block next in advance of the short block is occupied.
17. In an automatic train control system, speed control apparatus on a vehicle comprising a speed responsive device, permissive speed elements for establishing different ranges of varying permissive speeds, and separate controlling devices each normally governed jointly by one of the permissive speed elements and by said speed responsive device; brake controlling mechanism; and means comprising cooperating elements carried by the vehicle and located along the track for rendering said brake controlling mechanism selectively responsive to said controlling devices.
18. In an automatic train control system, speed control apparatus on a vehicle comprising a speed responsive device, permissive speed elements for establishing different ranges of varying permissive speeds, and separate circuit controllers each normally controlled jointly by one of the permissive speed elements and by said speed responsive device; an electrically operable brake controlling valve; a circuit for said valve in- cluding branches in multiple, each of said branches including one of said circuit controllers; and means partly on the vehicle and partly along the track for rendering said multiple branches selectively effective to control the brake controlling valve.
19. In an automatic train control system, speed control apparatus on a vehicle comprising a speed responsive device, permissive speed elements for establishing different ranges of varying permissive speeds, and separate circuit controllers each normally controlled jointly by one of the permissive speed elements and by said speed responsive device; an electrically operable brake controlling valve; a circuit for said valve, including branches in multiple, each of said branches including one of said circuit controllers; a stick relay associated with each multiple branch and acting when energized to render that branch effective to govern the operation of said brake controlling valve; means comprising elements partly on the vehicle and partly along the track for selectively energizing said relays; a normally closed circuit controller for governing the stick circuits of said relays; and means partly on the vehicle and partly along the track for opening normally closed circuit controller.
20. In an automatic train control system for railroads having regions or places where vehicles should travel at relatively low speeds, the combination with automatic speed control apparatus on the vehicle effective to compel the vehicle to gradually decrease its speed following initiation of the operation of said apparatus, of means partly on the vehicle and partly along the track in cooperative relation for initiating the operation of said apparatus at a predetermined point in the rear of said region of low speed independently of traffic conditions.
21. In an automatic train control system for railroads having a stretch of track which is divided into blocks of different lengths and in which there is a long block followed by one or more shorter blocks, the combination with an automatic speed control apparatus on a vehicle adapted to enforce gradually decreasing speed restrictions of an impulse device at the entrance to each block responsive to traffic conditions in the next block in advance, means on the vehicle influenced by said impulse device for governing the operation of said speed control apparatus, and a similar impulse device at an intermediate point in the long block effective to cause operation of said speed control apparatus at such point and thereby compel the vehicle to reduce its speed to accord with the braking distance afforded by the succeeding short block.
22. In an automatic train control system for railroads having a stretch of track which

is divided into blocks in which there is a long block followed by one or more shorter blocks, the combination with a vehicle, of automatic means partly on the vehicle and partly along the track for regulating the speed of the vehicle in the long block to prevent the vehicle entering the following shorter block at a speed greater than that corresponding to the braking distance afforded thereby, said means also acting to automatically reduce the speed of the vehicle in the long block to a predetermined minimum within the limits of said block whenever the next shorter block in advance is occupied.

23. In an automatic train control system for railroads having tracks provided with track sections each having a normally closed track circuit, the combination with automatic speed control apparatus on a vehicle adapted to change gradually from an initial condition to an ultimate condition and automatically enforce correspondingly decreasing limitations upon the speed of the vehicle during its progress along the track over a predetermined space interval, of means comprising impulse elements partly on the vehicle and partly distributed along the track at one or more intermediate points in said space interval for initiating and restoring said apparatus in accordance with the extent of unoccupied track in advance thereof.

24. In an automatic train control system for railroads having tracks divided into track sections each provided with a normally closed track circuit, a plurality of said track sections constituting braking distance for the vehicle, the combination with automatic speed control apparatus on a vehicle adapted when set into operation to gradually enforce varying restrictions on its speed, of impulse devices located at braking distance for the maximum speed of the vehicle from the entrance to a given track section and controlled by the track circuit of that track section, said impulse devices being adapted to influence the operation of the speed control apparatus on a passing vehicle, and one or more similar impulse devices located at less than such braking distance from the entrance to said given track section and also governed by the track circuit thereof, whereby the speed control apparatus on a vehicle approaching a given track section will be governed at successive points in accordance with traffic conditions therein.

25. In an automatic train control system for railroads having a stretch of track adjacent to a station and divided into track sections each having a track circuit, two or more of said track sections including a space interval corresponding to braking distance for the maximum speed of vehicles traveling over a track, the combination with automatic speed

control apparatus on a vehicle adapted to enforce varying restrictions on its speed, of impulse devices associated with said track sections, and trackway circuits for governing the impulse device of each track section by the track circuit of one or more than the number of track sections constituting said space interval, whereby the speed control apparatus on a vehicle approaching the station will be governed at frequent intervals in accordance with traffic conditions, but will always have braking distance between it and the next vehicle ahead.

26. In an automatic train control system for railroads having a block shorter than braking distance for the normal running speed of vehicles, speed governed brake control apparatus on a vehicle adapted when set into operation to compel the vehicle to conform to successively lower speeds, and means partly on the vehicle and partly on the track for causing operation of said apparatus a distance in the rear of the entrance to said block.

27. In an automatic train control system for railroads having tracks divided into blocks, speed control apparatus on a vehicle including a speed-responsive device driven from the wheels of the vehicle, and automatic means for rendering said apparatus effective adjacent to the entrance of some blocks and at a distance in the rear of the entrance of other blocks.

28. An automatic train control system for railroads having one or more blocks shorter than braking distance for the normal running speed of the vehicles comprising, brake control apparatus on a vehicle including a speed responsive device, and trackway means effective a distance in the rear of the entrance to said blocks for setting said apparatus into operation.

29. A train control system for railroads having one or more blocks shorter than braking distance for the speed which the vehicles may attain, the combination with automatic speed control apparatus on a vehicle adapted when set into operation to continue in operation until restored, traffic controlled means acting adjacent to the exit end of each block for restoring said apparatus, and trackway means for setting said apparatus into operation at a distance in the rear of the short blocks.

30. A train control system for railroads having blocks of different length, a brake control appliance on a vehicle, apparatus including permissive speed means and a speed responsive device for governing the brake control appliance, and trackway means for governing the permissive speed means on a vehicle at the entrance to some blocks and at a distance in the rear of the entrance of other blocks.

31. A train control system for railroads

- having blocks of different length, a brake control appliance on a vehicle, apparatus including permissive speed means and a speed responsive device for governing the 5
brake control appliance, said apparatus when set into operation continuing in operation until restored, and automatic means partly on the vehicle and partly on the track for setting the apparatus into operation 10 at the entrance to some blocks and at a distance in the rear of the entrance of other blocks, and means for restoring the apparatus at the exit end of each block dependent upon traffic conditions in the 15 next block in advance.
32. A train control system for railroads having a long block followed by a short block comprising, speed control apparatus on a vehicle, a track device located in the 20 long block and always acting to set said apparatus into operation and thereby regulate the speed of the vehicle as it enters the short block to conform with the braking distance afforded by the length of that 25 block.
33. A train control system for railroads having a long block followed by a short block comprising, speed control apparatus on a vehicle, trackway impulse device at 30 the entrance to said blocks having their controlling condition governed in accordance with traffic conditions in the next block in advance, and a similar impulse device at an intermediate point in the long block 35 permanently in its active stopping condition.
34. A train control system for railroads divided into blocks, automatic brake control apparatus on a vehicle including permissive speed means and actual speed means, and 40 permanently active trackway means active at a point in the rear of the entrance to some of said blocks for governing said apparatus.
35. In a train control system for railroads 45 having one or more blocks shorter than braking distance for the normal running speed of vehicles, speed governed brake control apparatus on a vehicle, means for initiating the operation of said apparatus a distance in the rear of the entrance to said short blocks, and traffic controlled means adjacent to the entrance to said blocks for restoring said apparatus.
36. A train control system having tracks 55 divided into blocks and provided with trackway impulse devices, said devices assuming an active stopping condition when their controlling circuits are broken, a short block, a continuously active impulse device located 60 a distance in the rear to said short block, and another impulse device at the entrance to said short block having its controlling circuit governed in accordance with traffic 65 conditions in the next block in advance.
37. A train control system governing the movement of vehicles through a long block followed by a short block comprising, automatic brake control means on a vehicle, and automatic means partly on the vehicle and partly on the track acting during the progress of the vehicle through the latter part of the long block to actuate the brake control means dependent upon the speed of the vehicle, said means acting to compel the vehicle to assume a speed less than a predetermined maximum at the entrance to the short block in conformity with the braking distance afforded by the length of that block. 70
38. In a train control system for railroads having regions where the vehicle should travel at low speeds under clear traffic conditions, speed governed brake control apparatus on a vehicle, and means partly on the vehicle and partly on the track for initiating the operation of said apparatus at a point 75 in the rear of said region of low speed, said point being located with regard to the distance required by the vehicle to reduce speed from the maximum attainable speed to the low speed required for said region. 80
39. In a train control system for railroads having regions where the vehicle should travel at low speeds under clear traffic conditions, automatic apparatus on a vehicle including changeable permissive speed means 85 determining when initiated a gradually reducing speed limit at which the vehicle may travel without an automatic brake application, and means for initiating a change of the permissive speed means upon the approach of the vehicle to said region of low speed. 90
40. In a train control system for railroads having regions where the vehicle should travel at low speeds under clear traffic conditions, automatic apparatus on a vehicle including a movable permissive speed element, governing means for said element operable to connect it to the wheels of the vehicle, and means for actuating the governing means upon the approach of the vehicle to said region of low speed. 100
41. In a train control system for railroads having regions where the vehicle should travel at low speeds under clear traffic conditions, brake control apparatus on a vehicle including a speed responsive device and adapted to enforce when operated a gradually reducing speed limit that the vehicle 105 can not exceed without an automatic brake application, and automatic means for setting said apparatus into operation at a distance in the rear of said region of low speed, such distance corresponding to the distance required for the vehicle to reduce speed from its maximum attainable speed to the low speed required for said region. 110
42. In a train control system for railroads having a portion of track divided into blocks shorter than braking distance for the nor- 115 120 125 130

- mal running speed of vehicles traveling thereon, speed governed brake control apparatus on a vehicle adjustable to establish continuing maximum speed limits for the 5 vehicle, means partly on the vehicle and partly on the track cooperating with said apparatus to enforce successively lower speeds as the vehicle approaches said portion of track, and other means for automatically adjusting said apparatus to establish 10 a continuing maximum speed limit corresponding to the braking distance afforded by the length of the blocks in said portion of track.
- 15 43. In a train control system for railroads having a portion of track divided into blocks shorter than braking distance for the normal running speed of vehicles traveling thereon, permissive speed means on the vehicle for determining the speed at which it may travel without an automatic brake application, means for automatically adjusting the permissive speed means to conform 20 with the length of the blocks in said portion of track, and other means partly on the vehicle and partly on the track for governing the permissive speed means independently of traffic conditions as the vehicle approaches said portion of track.
- 25 44. In a train control system for railroads having a portion of track divided into blocks shorter than braking distance for the normal running speed of vehicles traveling thereon, permissive speed means on a vehicle, means for causing operation of the 30 permissive speed means at a predetermined point in the rear of the entrance to said portion of track, and other means for independently adjusting the permissive speed means and for maintaining such adjustment while the vehicle travels through said portion of track.
- 35 45. In a train control system for railroads having a portion of track divided into blocks shorter than braking distance for the normal running speed of vehicles traveling thereon, speed governed brake control apparatus on a vehicle, means for governing said 40 apparatus in accordance with traffic conditions during the progress of the vehicle through said portion of track, means for adjusting the said apparatus independently of traffic conditions to establish a continuing maximum speed limit and for maintaining such adjustment while the vehicle travels through said portion of track, and other means for actuating said apparatus at a distance in the rear of said portion of track, whereby the vehicle is compelled to reduce speed to a maximum limit corresponding to the braking distance afforded by the length of the blocks before it enters said portion of track.
- 45 46. A train control system for railroads having tracks divided into blocks and also

having regions where low speed limits should be maintained regardless of traffic conditions, the combination with a vehicle and brake control means therefor, of automatic means partly on the vehicle and partly on the track for governing the brake control means in accordance with traffic conditions in the several blocks and for regulating the speed of the vehicle independently of traffic conditions in said regions, and means for compelling a reduction in the speed of the vehicle upon the approach to said regions.

47. A train control system for railroads having a low speed portion of track, the combination with apparatus on a vehicle comprising permissive speed means, an actual speed device, and a brake control appliance governed jointly thereby, said apparatus after being influenced into its active 80 condition from the trackway continuing to be active independently of such trackway influence until restored, of trackway means permanently in the active stopping condition for influencing said apparatus at a 85 predetermined point in the rear of said low speed portion of track.

48. Train control apparatus for railway vehicles comprising permissive speed means, a speed responsive device, a plurality of 90 circuit controllers having a continuing operative connection to the permissive speed means and the speed responsive device, a brake control circuit, and means for selectively rendering said circuit controllers 100 effective to govern said circuit.

49. In a train control system for railroads having a stretch of track adjacent to a station, said stretch being divided into short track sections, the combination with a brake controlling device on a vehicle, of means partly on the vehicle and partly on the track and effective at the entrances of said track sections for actuating said brake control device dependent upon the speed of 110 the vehicle and the extent of unoccupied track in advance thereof.

50. In a train control system for railroads having a stretch of track adjacent to a station, said stretch being divided into short track sections, brake control apparatus on a vehicle including a speed responsive device, and governing means for said apparatus including trackway means effective to influence the apparatus at the entrance to said track sections, a plurality of said track sections constituting braking distance for the vehicle, said trackway means being governed in accordance with the number of 115 such unoccupied track sections in advance of the vehicle.

51. In a train control system for railroads having a stretch of track adjacent to a station, said stretch being divided into short track sections, speed control apparatus on 130

5 a vehicle including a speed responsive device, and trackway means for governing said apparatus at the entrance to each track section in accordance with traffic conditions in two or more track sections in advance thereof.

10 52. In a train control system for railroads having a stretch of track adjacent to a station, said stretch being divided into short track sections, brake control apparatus on a vehicle including permissive speed means adapted to be driven from the wheels thereof, and automatic means for connecting and disconnecting the permissive speed means to the wheels of the vehicle adjacent to the entrance to each of said track sections in accordance with traffic conditions in a plurality of track sections in advance thereof.

15 53. A train control system for railroads having a stretch of track constituting a zone of congested traffic and divided into relatively short track sections, each having a track relay comprising, influence communicating means associated with each track section, and automatic means for energizing the influence communicating means of a given track section provided a number of track sections in advance thereof, sufficient to constitute braking distance for normal running speed, are not occupied.

20 54. A train control system for railroads having a stretch of track adjacent to a station divided into short blocks each having a track relay, a track impulse device at the entrance to each block, and separate controlling circuits for each track device governed by different numbers of track sections in advance of the corresponding track section.

25 55. A train control system for railroads having a stretch of track adjacent to a station divided into short blocks each having a track relay, a track impulse device at the entrance to each block, a control circuit for each track device governed by the track relays of one or more track sections in advance of the corresponding track section, and a separate control circuit for each track device governed by the track relays of one more track section than the first mentioned control circuit.

30 56. A train control system for railroads having a stretch of track adjacent to a station divided into short blocks each having a track relay, a track impulse device at the entrance to each block, the combination with train control apparatus on a vehicle, trackway means adapted to influence said apparatus at the entrance to each track section, and a control circuit for said trackway means of each track section including the front contacts of a plurality track relays in advance thereof.

35 57. A train control system for railroads

having a stretch of track adjacent to a station divided into short blocks each having a track relay, in combination, brake control apparatus on a vehicle, trackway means associated with each block adapted to influence said apparatus, and separate control circuits for the trackway means of each block governed in accordance with traffic conditions over different extents of track in advance thereof.

40 58. An automatic train control system for railroads having high speed territory and medium speed territory comprising, speed control apparatus on the vehicle for imposing a high, a medium or a low continuing speed limit which apparatus automatically applies the brakes of the train if the imposed speed limit is exceeded; and means partly on the vehicle and partly along the trackway for imposing the high speed limit under clear traffic conditions and imposing the low speed limit under danger traffic conditions in high speed territory, and for imposing the medium speed limit under clear traffic conditions and imposing a low speed limit under danger traffic conditions in said low speed territory.

45 59. A system for controlling the movement of vehicles through a stretch of track adjacent to a station, said stretch being divided into short track sections, each having a track relay, comprising car-carried train control apparatus, a trackway restoring control circuit for governing said apparatus associated with each track section and including a front contact of the track relay of the corresponding section and one or more sections in advance thereof, and an operating control circuit associated with each track section and including a front contact of one more track relay in advance of the corresponding track section than the track relays governing the restoring control circuit.

50 60. In a train control system for governing the movement of vehicles through stations comprising, in combination with a plurality of short track sections each having a track circuit, brake control apparatus on a vehicle, trackway means for influencing said apparatus at the entrance to each track circuit, said trackway means having distinctive controlling conditions for initiating and for restoring said apparatus, and means governed by different numbers of track circuits in advance for governing the trackway means of each track circuit.

55 61. A system for regulating train movement through stations comprising, in combination with a plurality of short track sections each having a track circuit, trackway means adapted to transmit controlling influences to a passing vehicle as it enters each track circuit, and speed governed brake control apparatus on a vehicle adapted to

establish different speed limits and governed by said trackway means, said trackway means and apparatus cooperating to establish speed limits variable in the several 5 track circuits dependent upon the number of unoccupied track circuits in advance.

62. A system for regulating train movement through stations comprising, in combination with a plurality of short track sections, each having a track circuit, car-carried apparatus including a speed responsive device and brake control means governed thereby, and trackway means responsive to the presence and location of vehicles for governing said apparatus during the progress of the vehicle through said short track circuits.

63. An automatic train control system for railroads comprising, car-carried speed control apparatus including means for gradually restricting the speed of the vehicle from a high to a lower value during the progress of the vehicle, said apparatus also including another independently operable 25 means for gradually restricting the speed of the train during its progress along the track from a medium speed to a low speed limit, means for applying the brakes of the train if the imposed speed limit is exceeded, 30 and trackway means effective under predetermined conditions of traffic ahead for causing said first mentioned means to be initiated when the train gets within a predetermined distance of another train ahead 35 and for initiating said another means when the train gets within another and shorter distance of said another train ahead.

64. A system for regulating train movement through stations comprising, in combination with a plurality of track sections each having a track circuit, car-carried apparatus adjustable to establish different maintained maximum speed limits, trackway means effective at a predetermined point with respect to the station for adjusting said apparatus, and other trackway means associated with said track circuits for governing the apparatus in accordance with the extent of unoccupied track in advance of the vehicle 50 comprising trackway impulse transmitting means associated with said track circuits and governed by a number of track circuits in advance thereof, and car-carried apparatus including permissive speed means influenced 55 by said trackway means, a speed responsive device, and brake control means governed jointly by the permissive speed means and the speed responsive device.

65. A system for governing train movement through stations comprising, cooperating means on a vehicle and on the trackway adjacent to the station for automatically limiting the speed of the vehicle as it approaches and passes through the station in conformity with the varying speeds followed

by the vehicle in making such a movement safely under manual control.

66. The combination with a curved track and a track circuit at the curve, of train speed control apparatus on the vehicle including brake control means, and trackway means at the approach to said curve always active to restrict the speed of the vehicle, and means effective beyond the curve and at the entrance end of said track circuit for releasing said train from such restriction effective only if said track circuit is not occupied.

67. In a traffic controlling system for railroads having curves in the track over which the speed of vehicles should be limited, vehicle-carried apparatus comprising a speed responsive device and a brake setting appliance governed thereby, said apparatus being adapted to enforce varying restricted speed limits conforming with those existing during retardation of the vehicle under safe manual control, and a trackway means for actuating said apparatus upon the approach of the vehicle to said curves.

68. A system for governing the speed of vehicles around curves comprising, car-carried apparatus adjustable to establish different maximum speed limits that persist independently of trackway control until the adjustment is changed, and trackway means operating a distance in the rear of said curves for adjusting said apparatus to select the maximum speed limit conforming to the curve.

69. A system for governing the movement of vehicles around curves, comprising car-carried brake control apparatus, and trackway means effective a distance in the rear of the curve and permanently in condition to cooperate with the said apparatus, said trackway means cooperating with the car-carried apparatus to cause an automatic brake application if the vehicle exceeds successively lower predetermined speed limits upon its approach to the curve.

70. A system for governing the movement of vehicles around curves, comprising a safety appliance for excessive speed on a vehicle, said appliance being operable to prescribe automatically a series of successively lower speed limits and apply the brakes if the vehicle exceeds such speed limits, and trackway means located a distance in the rear of the curve for governing the operation of said appliance.

71. A system for governing the movement of vehicles around curves comprising, in combination with a vehicle and means thereon limiting its normal running speed, trackway means located at a control point with respect to the curve dependent on the normal running speed of said vehicle approaching the curve and the safe speed for the curve, and car-carried brake-setting means cooperating with the trackway means and having

its operation dependent upon the existing speed of the car.

72. In a train control system, the combination with a curved portion track divided into track sections each provided with a normally closed track circuit, trackway means associated with said track sections and governed by the track circuits thereof for transmitting controlling influences to passing vehicles, and permanently active trackway means effective a distance in the rear of the curve for transmitting a stopping influence to passing vehicles irrespective of traffic conditions, whereby the vehicle is compelled to reduce speed upon the approach to the curve.

73. In a train control system, in combination with a curved portion of track, permanently active means on the trackway effective a distance in the rear of the beginning of the curve and adapted to communicate a stopping influence to passing vehicles, and speed governed brake-setting apparatus on a vehicle having its operation initiated by said influence and continuing in operation until restored.

74. In a train control system, in combination with a curved portion of track, car-carried apparatus including permissive speed means adjustable to establish different persisting speed limits, trackway means for governing said apparatus through said portion of track in accordance with traffic conditions, trackway means for adjusting permissive speed means to a maximum speed condition corresponding to the safe speed for the curve, and trackway means effective a distance in the rear of the curved portion of a track for governing said apparatus independently of traffic conditions.

75. In a train control system, in combination with a curved portion of track, a brake control device on the vehicle, and means partly on the vehicle and partly on the track for operating said device upon the approach and during the passage of the vehicle around the curve if it exceeds speeds corresponding to those existing during such movement under safe manual control.

76. In a train control system, in combination with a curved portion of track, a brake control device on a vehicle, speed responsive means, control means influenced from the trackway dependent upon traffic conditions in advance for operatively coupling the brake control device and speed responsive means for operation at an excessive speed, said control means regulating the speed of the vehicle during its progress over said curved portion of track, and permanently active trackway means effective at a distance in the rear of said portion of track for also influencing the said control means.

77. In a train control system, in combination with a curved portion of track, a

brake control apparatus on a vehicle including changeable permissive speed means adapted to establish speed limits above which the brakes of the vehicle are applied, and means partly on the track and partly on the vehicle for changing the permissive speed means to a speed limiting condition corresponding to the safe speed for movement of vehicles over said curved portion of track, said last mentioned means being effective before the vehicle reaches said portion of track and continuing in operation until restored and automatic means for restoring said apparatus after the vehicle has passed said portion.

78. In a train control system, in combination with a curved portion of track, a brake control apparatus on a vehicle conditioned from the trackway and operable to cause an automatic brake application dependent upon the speed of the vehicle, permanently active trackway means for governing said apparatus at a distance in the rear of the curve, and other similar trackway means controlled in accordance with traffic conditions for also governing said apparatus during the progress of the vehicle through said curved portion of track.

79. In a train control system, in combination with a curved portion of track, normally inactive brake control apparatus on a vehicle, control means on the vehicle for governing the operation of said apparatus, and adapted when rendered active to continue active until restored, means for restoring said apparatus after the vehicle has passed said portion of track, and permanently active trackway means acting to influence the control means on the vehicle at a distance in the rear of the entrance to said portion of track.

80. In an automatic train control system, track equipment for curved tracks divided into blocks provided with track circuits, comprising means governed by said track circuits and assuming different controlling conditions dependent on the presence or absence of trains in advance, and other trackway means permanently in the stopping condition and effective at a predetermined control point with reference to the beginning of the curve.

81. In a train control system, the combination with the track and a curve therein, a brake control device on a vehicle tending to assume a brake applying condition, control means on the vehicle normally maintaining the said device inactive, trackway means effective at a distance in the rear of the entrance to said curve, for influencing said control means on the vehicle, and other trackway means located beyond said curve for restoring said control means to normal only if traffic conditions ahead are clear.

82. In a train control system, the com-

bination with the track and a curve therein, a brake control magnet, a series of independent normally closed circuits for governing said magnet, and trackway means for interrupting a circuit of said series at a control point in the rear of the entrance to said curve and continuing such interruption thereafter independently of the trackway means until restored.

- 10 83. In a train control system, the combination with the track and a curve therein, car equipment comprising a brake control magnet, normally closed circuits governing said magnet, and a speed responsive device, and track equipment comprising permanently active means effective at a control point in the rear of the entrance to said curve for causing a continuing interruption of one of said circuits, said control point being located with regard to the distance required to bring the vehicle from a maximum speed to a safe speed for the curve, and trackway means for discontinuing such interruption of said circuit.
- 15 84. In a train control system, the combination with the track and a curve therein, car equipment comprising, a normally energized brake control magnet, a speed responsive device, a control means including normally closed circuits for bringing the brake control magnet under the influence of the speed responsive device and thereby cause an automatic brake application when the vehicle exceeds the prescribed speed limit, and track equipment comprising means locally effective at a distance in the rear of the entrance to the curve for rendering said control means on the vehicle active regardless of traffic conditions and for restoring said control means after the vehicle has passed said curve.

20 85. A train control system for railroads having restricted speed territory, comprising, automatic brake setting means on a vehicle, and means partly on the vehicle and partly on the track acting automatically upon the approach of the vehicle to said territory to actuate the brake setting means dependent upon the speed of the vehicle and its location with respect to its entrance to said territory, whereby the vehicle is forced to reduce speed to a limit suitable for said territory.

25 86. A train control system for railroads having restricted speed territory, comprising, brake governing apparatus on a vehicle including permissive speed means and cooperating actual speed means, said apparatus being adapted to be influenced to establish a restricted speed limit persisting until restoration thereof, and means partly on the vehicle and partly on the track for influencing said apparatus at a point in the rear of the entrance to said territory, said trackway means also acting to restore

the brake governing apparatus near the exit from said territory, said point being located with respect to the distance required by the vehicle to reduce speed from its normal running speed to the limited speed required for 70 said territory.

87. A train control system for governing train movements through restricted speed territory, comprising, apparatus on a vehicle including a speed responsive device, permissive speed means adapted to be driven from the wheels of the vehicle, and brake governing means responsive to the joint influence of the speed responsive device and permissive speed means, and permanently active trackway means adapted to cause the connection of the permissive speed means to the wheels of the vehicle as it passes a point in the rear of the entrance to said territory.

88. A train control system for railroads having portions of track over which the vehicles should not exceed restricted speeds, comprising in combination, automatic speed control apparatus on a vehicle effective when operated to cause an automatic brake application if the vehicle exceeds successively lower speed limits in its subsequent travel, trackway means for governing said apparatus in accordance with traffic conditions, and similar trackway means permanently in the active condition for causing operation of said apparatus at a distance in the rear of the entrance to said restricted speed portions of track.

89. An automatic train control system for railroads having tracks divided into blocks and having portions of track over which restricted speed should be maintained, comprising in combination, a brake control device on a vehicle, automatic means partly on the vehicle and partly on the track automatically governed in accordance with traffic conditions for actuating the brake control device in the several blocks dependent upon the speed of the vehicle and its location with respect to the exit end of said blocks, and permanently active trackway means for also governing the brake control device on the vehicle as it approaches said portions of track.

90. A train control system for railroads having tracks divided into blocks each provided with a normally closed track circuit, said railroad having regions where the vehicle should travel at restricted speed regardless of traffic conditions ahead, comprising, speed governed brake control apparatus on a vehicle, means for governing said apparatus in each block in accordance with traffic conditions in the next block in advance, and means for operating the said apparatus independently of traffic conditions as the vehicle approaches said low speed regions.

91. A train control system for railroads having tracks divided into blocks each provided with a normally closed track circuit, said railroad having regions where the vehicle should travel at restricted speed regardless of traffic conditions ahead, comprising speed control apparatus on a vehicle including changeable permissive speed means adapted to determine the speed at which the vehicle may travel without a brake application, means for governing said permissive speed means as the vehicle passes through the several blocks in conformity with the presence or absence of vehicles ahead, and permanently active means for causing a change of the permissive speed means to a lower speed condition as the vehicle passes a point in the rear of the entrance to said low speed regions. 70
92. A train control system for railroads having tracks divided into blocks each provided with a normally closed track circuit, said railroad having regions where the vehicle should travel at restricted speed regardless of traffic conditions ahead, comprising brake control apparatus on a vehicle including a speed responsive device, means partly on the vehicle and partly on the track for governing said apparatus in the several blocks to conform with traffic conditions in advance, and similar means permanently in the active condition for also causing operation of said apparatus during the approach of the vehicle to said low speed regions. 80
93. A train control system for railroads having tracks divided into blocks each provided with a normally closed track circuit, said railroad having regions where the vehicle should travel at restricted speed regardless of traffic conditions ahead, comprising apparatus on a vehicle including permissive speed means and cooperating actual speed means adapted to establish a number of limiting speeds which the vehicle can not exceed without a brake application, means for governing said apparatus in accordance with traffic conditions, and similar means for causing operation of said apparatus as the vehicle approaches the low speed regions. 95
94. A train control system for railroads having tracks divided into blocks of different length each provided with a track circuit, comprising trackway means associated with each block and having a control circuit governed by the track circuit of the block next in advance, and similar permanently active trackway means effective at an intermediate point in some of said blocks. 105
95. A train control system for railroads having tracks divided into blocks of different length each provided with a track circuit, comprising trackway means adjacent to the entrance to each block and having its controlling condition dependent in succession during the passage of the vehicle thereby upon the presence or absence of other vehicles in the corresponding block and the next block in advance, and similar permanently active trackway means located at an intermediate point in some of the blocks. 120
96. In a train control system for railroads having portions of track over which the vehicle should travel at restricted speeds, an automatic brake control appliance on the vehicle, means partly on the vehicle and partly on the track cooperating to cause operation of said appliance when the vehicle exceeds a corresponding restricted speed, said means being automatically rendered effective while the vehicle travels through said portions of track, and permanently conditioned trackway means also acting to cause operation of said appliance during the approach of the vehicle to said regions. 125
97. A train control system for governing the movement of vehicles through restricted speed regions, comprising, brake control apparatus on a vehicle including permissive means and actual speed means and adjustable to establish continuing maximum speed limits, trackway means for adjusting said apparatus as the vehicle enters said regions and thereby establish a maximum speed limit conforming with the safe speed for that region, and other trackway means cooperating with said apparatus as the vehicle approaches said regions. 130
98. A train control system for governing the movement of vehicles through restricted speed regions, comprising, apparatus on a vehicle including a speed responsive device for governing the brakes thereof, permanently conditioned trackway means for actuating the apparatus as the vehicle approaches said regions, and means for causing said apparatus to establish a continuing maximum speed limit during the progress of the vehicle through said regions. 135
99. In a train control system, the combination with a plurality of blocks, some of said blocks constituting a low speed territory where restricted speeds should be maintained regardless of traffic conditions, speed governed brake control apparatus on a vehicle, means partly on the vehicle and partly on the track for governing operation of said apparatus in accordance with traffic conditions in the several blocks, means for adjusting the apparatus to establish a continuing maximum speed limit, and permanently conditioned trackway means for operating said apparatus as the vehicle approaches said low speed territory. 140
100. In a train control system, the combination with a plurality of blocks, some of said blocks constituting a low speed territory where restricted speeds should be maintained regardless of traffic conditions, brake control apparatus on a vehicle including changeable 145

permissive speed means, means for initiating and restoring the permissive speed means during the progress of the vehicle through the several blocks dependent upon traffic 5 conditions, similar means acting to cause operation of the apparatus regardless of traffic conditions as the vehicle approaches said territory, and means partly on the vehicle and partly on the track cooperating to 10 adjust the permissive speed means to establish a continuing maximum speed limit for the vehicle during its travel through said territory.

101. In a train control system, the combination with a plurality of blocks, some of said blocks constituting a low speed territory where restricted speed should be maintained regardless of traffic conditions, brake control apparatus on a vehicle including 20 permissive speed means adapted to assume different initial maximum speed conditions and to be changed from the existing initial condition to an ultimate low speed condition, means for adjusting the initial condition of 25 the permissive speed means, traffic controlled means for initiating its change and for restoring it to the selective initial condition, and permanently conditioned trackway means effective a distance in the rear of the 30 entrance to said territory for initiating a change of the permissive speed means.

102. A train control system for railroads having a stretch of track adjacent to a station divided into short track sections each 35 having a track circuit, comprising in combination with speed control apparatus on a vehicle, means controlled by said track circuits for governing the apparatus in accordance with traffic conditions, and means 40 for adjusting said apparatus to establish a continuing maximum speed limit conforming with the braking distance afforded by a predetermined number of said track sections.

103. A train control system for railroads having a stretch of track adjacent to a station divided into short track sections each having a track circuit, comprising, apparatus on a vehicle including permissive speed 50 means for governing the brakes thereof, means controlled by said track circuits for initiating and restoring the permissive speed means dependent upon traffic conditions in advance, and means for adjusting the permissive speed means to establish a speed limit conforming with the braking distance afforded by a predetermined number of track sections.

104. In a train control system, the combination with a stretch of track adjacent to a station divided into short track sections a plurality of which constitute braking distance for the vehicles, apparatus on a vehicle 60 for governing the brakes thereof changeable 65 from an initial condition and continuing in

operation until restored, and means partly on the vehicle and partly on the track for initiating and restoring said apparatus, such initiation occurring braking distance in the rear of an occupied track section, and the 70 restoration when the number of unoccupied track sections in advance of the vehicle is at least as many as said plurality.

105. In a train control system, the combination with a stretch of track adjacent 75 to a station divided into short track sections, a plurality of which constitute braking distance for the vehicles, train control apparatus on a vehicle adapted to continue in operation until restored, and automatic means 80 for restoring the apparatus at the entrance to each block when the number of unoccupied track sections in advance of the vehicle is at least equal to said plurality.

106. In a train control system, the combination with a stretch of track adjacent to a station divided into short track sections, a plurality of which constitute braking distance for the vehicles, brake control apparatus on a vehicle including a speed responsive device, and means partly on the vehicle and partly on the track effective at the entrance to each track section for setting said apparatus into operation whenever there is only said plurality of track sections in advance of the vehicle which are unoccupied.

107. In a train control system, the combination with a stretch of track adjacent to a station divided into short track sections, a plurality of which constitute braking distance for the vehicles, apparatus on a vehicle including changeable permissive speed means for governing the brakes thereof, said means continuing in a changed condition 100 until restored, and means partly on the vehicle and partly on the track for restoring the permissive speed means at the entrance to a track section when a number of track sections in advance of the vehicle and constituting braking distance therefor are unoccupied.

108. A train control system comprising, car apparatus including a speed responsive device, a plurality of circuit controllers 115 opened thereby as the vehicle exceeds corresponding speeds, a brake control circuit, and stick relays for placing said circuits selectively under the control of said circuit controllers, and trackway means for governing 120 the relays.

109. Car apparatus for train control systems comprising a speed responsive device, a movable element shifted to different positions by said device in accordance with the speed of the vehicle, circuit controllers opened by said element as the vehicle exceeds corresponding speeds, a normally closed brake control circuit, and a plurality 125 of relays adapted when energized to place 130

said circuit under the control of a selected circuit controller.

110. Car apparatus for train control systems comprising a plurality of circuit controllers opened as the car exceeds corresponding speeds, a normally closed brake control circuit having a branch through each circuit controller, and a relay for making and breaking each branch when energized and deenergized respectively, said brake control circuit being interrupted and the brakes automatically applied when all of the relays are deenergized.

111. Car apparatus for train control systems comprising a normally energized brake control device, a circuit therefor having multiple branches, means for braking each branch when the car exceeds a corresponding speed, a relay making and breaking each branch when energized and deenergized respectively, and trackway means for governing the relays.

112. In a train control system, the combination with a curved track, brake control apparatus on a vehicle including permissive speed means and an actual speed device which cooperate while the apparatus is active to enforce gradually decreasing speed limits, and trackway means rendering said apparatus active a distance in the rear of the beginning of said curve.

113. In a train control system, the combination with a curved track, brake control apparatus including permissive speed means changeable to establish a limiting speed which the vehicle can not exceed without an automatic brake application, said permissive speed means continuing in effect after once initiated until restored, and trackway means for initiating a change of the permissive speed means at a control point braking distance in the rear of the beginning of the curve and for restoring the permissive speed means near the exit end of said curve.

114. Car apparatus including a movable permissive speed device adapted to be operatively connected to the wheels of the car, a track having a curve therein, and means partly on the vehicle and partly on the track and always effective to connect said device to the wheels of the car as it passes a point braking distance in the rear of the beginning of the curve and to disconnect said device from the wheels after the vehicle has passed over said curve.

115. In a train control system, the combination with a manually controlled interlocked signal, a ramp adjacent to the signal having two sections, and means for controlling the energization of said sections separately.

116. In a train control system, the combination with a manually controlled interlocked signal, a ramp adjacent to the signal

having two sections, and means for at times energizing both sections and at other times deenergizing the advance section and connecting it to the track rails.

117. A system for governing the movement of trains past stations comprising, speed governed brake control means on a vehicle effective to establish a maximum limiting speed and also operable to influence lower speed limits, and means for initiating and restoring said apparatus at relatively close control points separated by less than braking distance for said maximum speed during the passage of the vehicle through the station.

118. A system for governing the movement of vehicles into and through stations comprising, brake control apparatus on a vehicle including changeable permissive speed means adapted to change from initial conditions to an ultimate condition during the progress of the vehicle over a predetermined distance, the stretch of track adjacent to the station being divided into track sections a multiple of which is substantially equal to said distance, and traffic controlled means for initiating and restoring the permissive speed means at each track section dependent on traffic conditions in advance thereof.

119. In a train control system, the combination with a speed control apparatus on a vehicle adapted to govern the brakes thereof in conformity with a braking curve, a plurality of track sections each shorter than said braking curve, and trackway means effective at the entrance to each track section for initiating and restoring said apparatus dependent upon the number of unoccupied track sections in advance thereof.

120. An automatic train control system for railroads divided into blocks by insulating joints comprising, car-carried apparatus including speed restricting means effective to apply the brakes if the imposed speed limit is exceeded, and trackway means for governing said car-carried apparatus including a track section of less length than braking distance, means associated with said track section and always active to restrict the speed of the train and means at the exit end of said section to continue or release automatically such restriction depending on traffic conditions ahead.

121. A system for governing the movement of trains through stations or other congested territory, comprising, speed governed brake control apparatus on a vehicle for limiting its normal running speed, and means including said brake control apparatus for applying the brakes of the vehicle at relatively close control points spaced apart less than braking distance for such maximum speed, said last mentioned means having its operation dependent upon the

speed of the vehicle and initiating and restoring controls from the track dependent upon the extent of unoccupied track in advance thereof, said means imposing gradually reducing speed limits as the vehicle approaches another train ahead.

122. A system for governing the movement of trains through stations or other congested territory, comprising, a portion 10 of track divided into short track sections, brake control means on a vehicle for limiting its maximum speed to conform with the braking distance afforded by a predetermined member of track sections, and 15 track means associated with each track section and governed in accordance with the presence or absence of vehicles in a limited number of said track sections for initiating operation of said brake control means, 20 said brake control means when set into operation, changing to an ultimate condition after an interval of delay and imposing a low speed limit.

123. In a railway automatic vehicle speed 25 control, in combination; a trackway having sections necessitating limited vehicle speeds under clear conditions; a vehicle for movement thereon; means partly along the trackway and partly on the vehicle whereby the 30 speed of the vehicle is limited at said sections, the means on the trackway including a normally deenergized ramp followed by a normally energized ramp spaced apart a distance corresponding to the necessary 35 limited vehicle speed, a track circuit, said normally energized ramp being located at the entrance to said track circuit and being controlled thereby.

124. In a railway automatic vehicle speed 40 control, in combination; a trackway having sections necessitating limited vehicle speeds under clear conditions; a vehicle for movement thereon; means partly along the trackway and partly on the vehicle whereby the 45 speed of the vehicle is limited at said sections, the means on the trackway including ramp members spaced apart a distance corresponding to the necessary limited vehicle speed, one of said ramp members being de- 50 energized and the other energized, a track circuit, the energized ramp being located at the entrance to said track circuit and being de-energized if the track circuit is occupied.

125. In a railway automatic train speed 55 control, in combination; a trackway divided into sections each having a track circuit; a

device on the vehicle moved in accordance with the actual speed thereof; another device on the vehicle having an initial maximum condition and an ultimate minimum 60 condition and moved after release by the movement of the vehicle in accordance with the permissible speed thereof; means governed by the conjoint action of the said devices whereby the speed of the vehicle is 65 governed; means along the trackway for releasing the second device and being normally active to release; means along the trackway for restoring the second device to maximum condition, the last two mentioned 70 means being positioned a distance apart longitudinally of the trackway such that any desired movement of the second mentioned device from maximum to minimum will be 75 caused before restoration of the second mentioned device to maximum, and the means along the trackway for restoring the second device being located at the entrance to a track circuit and being governed thereby.

126. In a railway automatic train speed 80 control, in combination; a trackway divided into sections each having a track circuit; a vehicle for movement thereon; means on the vehicle for controlling the speed thereof and means on the trackway for governing 85 the vehicle controlling means, the means on the trackway including two ramp members spaced longitudinally of the trackway a distance apart corresponding to the control desired, one of said ramp members being de- 90 energized and the other being normally energized, and the energized ramp being located at the entrance to a track circuit and being de-energized if said track circuit is 95 occupied.

127. In a railway automatic train speed control, in combination; a trackway divided into sections each having a track circuit; a vehicle for movement thereon; means on the vehicle for causing a gradual reduction in 100 speed of the vehicle and means, including spaced members on the trackway, one of which is deenergized and the other of which is normally energized for causing any desired amount of reduction in speed of the vehicle, the amount being determined by varied spacing of the members longitudinally of the trackway, and the normally energized member being located at the entrance to a track 105 circuit and being de-energized if the track circuit is occupied.

WINTHROP K. HOWE.
